UNITED STATES PATENT OFFICE

ARTHUR J. RAY, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

MULTIOFFICE AUTOMATIC TELEPHONE SYSTEM

Application filed November 4, 1922, Serial No. 599,022. Renewed November 19, 1926.

The present invention relates to multi-office automatic telephone systems in general, but is concerned more particularly with multi-office automatic telephone systems in which there are two different types of automatic offices, and the principal object, stated briefly, is the production of new and improved circuit arrangements for handling calls which come into a so-called "panel" office from a so-called "step by step" office.

In order to explain the necessity for an arrangement such as is contemplated by the present invention, it may be stated that, in many cities served by a multi-office telephone system, for reasons which vary with different cases, two widely different kinds of automatic equipment, namely; the "step by step" type and the "panel" type, are installed in different offices of the system. When this is done, special arrangements must be made when calls originating in a step by step automatic office (in which the switches are directly controlled and operate in a step by step manner) are intended for a panel office (in which the switches are power-driven and are operated according to the well-known retractive control system).

In order to meet the situation, each of the trunks from a step by step automatic office to a panel office is carried to the panel office and terminated in a trunk circuit individual to an incoming panel selector. There is a secondary switch associated with each trunk circuit. These secondary switches have common access to a plurality of register sets and an idle register set is seized by one of these secondary switches when the trunk associated with the secondary switch is seized. Then, when the remaining digits in the desired number are received, the register set is correspondingly operated, after which the register set is temporarily associated with an idle sender and the number which is set up on the register is quickly transferred to the set-up relays of the sender. The sender is then associated with the incoming selector of the trunk over which the call came in and operates the incoming selector and a final selector to complete the connection.

Referring now to the accompanying drawings, comprising Figs. 1-13, inclusive, Fig. 1 shows certain switching apparatus which is assumed to be in a step by step automatic office; Figs. 2-12, inclusive, show certain switching apparatus which is assumed to be located in a panel office which is interconnected by trunks, such as the one comprising conductors 72 and 73, with the step by step automatic office containing the equipment shown in Fig. 1; and Fig. 13 is a layout showing how the sheets of drawings fit together.

The equipment shown in Fig. 1 is automatic equipment of the well-known type and comprises the substation A, of which the line terminates in the individual line switch C, the district selector D accessible to the line switch C, the office selector E (denoted by the dotted rectangle bearing that reference character) accessible to the selector D, and the automatic repeater F which is accessible to the office selector E and which is individual to the trunk comprising conductors 72 and 73.

The inter-office trunk comprising conductors 72 and 73, terminates at the panel office in the trunk circuit TC, Fig. 2, which is individual to the incoming selector, Fig. 4. The incoming selector, Fig. 4, has access to a number of final selectors, of which the final selector shown in Fig. 5 is one.

The secondary switch SS, Fig. 2, associated with the trunk circuit TC has access to a number of register sets, of which the register set shown in Fig. 6 is one. This register set is adapted to register the four digits in the called subscriber's number.

The register allotter, Fig. 7, allots the register sets one at a time after the full number has been dialled on each one and causes the energization of the register connecting relay, such as 428', so as to connect the conductors of the register set through to the common transfer control circuit, Fig. 8.

Associated with the transfer control circuit, Fig. 8, there are six finder selectors, of which one is shown in Fig. 9. The trunk finding element of each of these finder selectors has access to all the incoming selectors

of the associated group, and the selector element has access to a group of senders of which the sender shown in Figs. 10 and 11 is one.

5 The finder selector allotter, Fig. 12, is common to the six finder selectors and allots them for use one at a time.

The line switch C, Fig. 1, is mechanically of the well-known rotary type in which the 10 wipers have no normal position and move in a forward direction only. The secondary switch SS, Fig. 2, as well as the register allotter, Fig. 7, is mechanically similar to the line switch C.

15 The selector switches D and E, Fig. 1, are step by step automatic switches of the well-known vertical and rotary type and each has 100 sets of bank contacts arranged in ten horizontal rows or levels. The registers R and R', 20 Fig. 6, are mechanically similar to the selectors D and E, Fig. 1.

The panel type selector switches which are shown in Figs. 4 and 5, may be of the type described in Patent No. 1,123,696 to Craft 25 et al, issued January 5, 1915. The finder and selector switches of the finder-selector link, Fig. 9, are identical with each other except as regards the number of brushes provided, and are similar to the selector switches 30 shown in Figs. 4 and 5, with the exception that only one set of brushes is provided on each of the switches of the finder-selector link and, since the brushes are normally tripped, no trip magnet is provided.

35 The sequence switches shown in the present disclosure are of the type described in Patent No. 1,127,808, issued February 9, 1915 to Reynolds et al.

The apparatus, having been described generally, will now be described in connection with a detailed description of its operation. For this purpose, it will be assumed that the subscriber at substation A, Fig. 1, whose line terminates in the step by step automatic office, desires to obtain connection with the subscriber at substation A', Fig. 5, whose line terminates in the panel automatic office. It will be assumed by way of illustration that the panel office is office 26 and, that the number of the subscriber at substation A' is 3737. Consequently, the complete number to be dialled is 26-3737, a dash being inserted ordinarily between the office designation and the subscriber's number to enable the calling subscriber to remember the desired number without difficulty.

When the receiver is removed at substation A, line relay 6 energizes over line conductors 2 and 4. Upon energizing, line relay 6 places ground on private normal conductor 3 at armature 10', thereby making the calling line busy and closing a circuit for switching relay 5 and stepping magnet 7 in series. As a further result of the energization of line relay 6, it connects test wip-

er 12 to the junction of switching relay 5 and stepping magnet 7 at armature 8'.

In case the trunk upon which the wipers of the line switch are standing is idle, switching relay 5 energizes immediately. Assuming the trunk to be busy, however, switching relay 5 is short circuited and does not energize, and the wipers are rotated step by step by the buzzer-like action of stepping magnet 7, which operates from ground on the busy test contacts encountered by test wiper 12. When an idle trunk is reached, which trunk it will be assumed is the one comprising conductors 17-19, inclusive, switching relay 5, being no longer short circuited, energizes in series with stepping magnet 7. Stepping magnet 7, however, does not energize at this time on account of the high resistance of switching relay 5. Switching relay 5, upon energizing, opens a point in the test circuit 80 and prepares the holding circuit at armature 9, and at armatures 8 and 10 disconnects line conductors 2 and 4 from the winding of line relay 6 and ground, and extends them by way of wipers 11 and 13, bank contacts 14 and 16, conductors 17 and 19, and armatures 42 and 45 and their resting contacts to the upper and lower windings of line relay 25 of the selector D.

Line relay 25 now energizes over the calling subscriber's loop and closes at armature 36 a circuit for release relay 26. Upon energizing, release relay 26 opens a point in the circuit of release magnet 30 and prepares a circuit for vertical magnet 35 at armature 38, and at armature 37 places ground on release trunk conductor 18, thereby closing the usual holding circuit for switching relay 5 of the line switch C before slow acting line relay 6 has had time to deenergize.

When the calling subscriber operates his calling device in accordance with the first digit 2 in the desired number of the desired office, the circuit of line relay 25 is opened a corresponding number of times. Each time line relay 25 deenergizes in response to one of the interruptions thereby produced, it closes a circuit for vertical magnet 35 as follows: From ground by way of the resting contact of armature 44 and said armature, armature 36 and its resting contact, armature 38 and its working contact, relay 27, and vertical magnet 35 to battery. By the operation of vertical magnet 35, the wipers 46-48, inclusive, are raised opposite the fifth level of bank contacts. Relay 27 is energized in series with vertical magnet 35 and, being slow acting, retains its armature attracted throughout the vertical movement. As a result of the energization of relay 27, it closes a circuit at armature 39 for stepping relay 28 by way of off normal contacts 34, which close upon the first vertical step, and interrupter contacts 33. Stepping relay 28, upon energizing, closes a locking circuit for itself 130

at armature 40, and at armature 41 prepares a circuit for rotary magnet 32.

At the end of the vertical movement, slow acting relay 27 deenergizes and completes the circuit of rotary magnet 32 at armature 39. 5 Rotary magnet 32, upon energizing, advances the wipers 46-48, inclusive, into engagement with the first set of bank contacts in the selected level, and, near the end of its stroke, 10 opens the circuit of stepping relay 28 at interrupter contacts 33. Stepping relay 28, upon deenergizing, opens the circuit of rotary magnet 32 at armature 41, whereupon rotary magnet 32 deenergizes also and closes 15 its interrupter contacts 33 again. In case the trunk terminating in the first set of bank contacts is idle, switching relay 29 energizes immediately. Assuming the trunk to be 20 busy, however, switching relay 29 is short circuited by the ground potential encountered by test wiper 47 and stepping relay 28 energizes from this same ground potential and closes the circuit of rotary magnet 32 again, whereupon the switch wipers are 25 rotated into engagement with the next set of bank contacts.

This alternate operation of stepping relay 28 and rotary magnet 32 continues until an 30 idle trunk is reached, which trunk it will be assumed is the one extending to the second or office selector E, whereupon switching relay 29, being no longer short circuited, energizes in series with stepping relay 28. Stepping relay 28, however, does not energize 35 at this time on account of the high resistance of switching relay 29. Switching relay 29, upon energizing, opens a point in the test circuit and prepares the holding circuit at armature 43; disconnects ground from armature 35 of line relay 2 at armature 44, thereby 40 opening the circuit of release relay 26; and at armatures 42 and 45 disconnects conductors 17 and 19 from the windings of line relay 25, and extends them by way of wipers 45 46 and 48 to the line relay of the selector E. The line and release relays (not shown) of the selector E now energize and prepare the switch for operation, and the latter relay grounds the release trunk conductor, therefore 50 by establishing the usual holding circuit for the switches C and D.

In response to the calling of the second 55 digit 6 in the number of the desired office, the wipers of the office selector E are raised opposite the level of bank contacts in which the trunks extending to the panel office terminate, and are then rotated in search of an 60 idle trunk in the usual manner. In this case, it will be assumed that the trunk extending to the repeater F and comprising conductors 49-51, inclusive, is the one selected. That being the case, line relay 62 of the selector F energizes over the calling subscriber's loop and through the normally closed contacts 65 controlled by armatures 65 and 66 of revers-

ing relay 61, and closes a circuit for release relay 63 at armature 67. Release relay 63, upon energizing, prepares a circuit for relay 64 at armature 70, and at armature 69 places ground on release trunk conductor 50, thereby establishing the usual holding circuit for the switches C, D, and E. As a further result of the energization of line relay 62, it closes a bridge across the outgoing trunk conductors 72 and 73 at armature 68. This bridge, it 70 will be noted, includes the right-hand windings of the repeating coil and the lower winding of the electro-polarized reversing relay 61. Reversing relay 61 does not energize at this time, however, for the reason that the 75 current flow in either winding opposes the current flow in the other winding.

In the panel office, line relay 102 energizes over conductors 72 and 73 and through the left-hand repeating coil windings and the 80 normally closed contacts controlled by armatures 109 and 110 of reversing relay 101, in response to the closure of the previously mentioned bridge across conductors 72 and 73 in the repeater F. Upon energizing, line relay 85 102 closes a circuit for release relay 103 at armature 112. Release relay 103, upon energizing, closes at armature 113 a circuit for switching relay 141 and stepping magnet 142 of the secondary switch SS in series as follows: From ground by way of the working contact of armature 113 and said armature, armature 117 and its resting contact, armature 120 and its resting contact, switching 90 relay 141, and stepping magnet 142 to battery. As a further result of the energization of release relay 103, it connects test wiper 149 to the junction of switching relay 141 and stepping magnet 142 at armature 115 by way 95 of the resting contact of armature 118 and said armature, armature 121 and its resting contact, and the resting contact of armature 145 and said armature.

In case the trunk upon which the wipers 100 of the secondary switch are standing is idle, switching relay 141 energizes immediately. Assuming the trunk to be busy, however, switching relay 141 is short circuited by the ground potential which is found on the test contact thereof by test wiper 149, and the 105 wipers are rotated step by step in search of an idle trunk by the buzzer-like action of stepping magnet 142. When an idle trunk is found, which trunk it will be assumed is the one comprising conductors 155-158, inclusive, and terminating in bank contacts 151-154, inclusive, switching relay 141 energizes over the above traced circuit in series 110 with stepping magnet 142. Stepping magnet 142, however, does not energize at this time on account of the high resistance of switching relay 141. Switching relay 141, upon energizing, opens a point in the test circuit and places ground on test wiper 149 at armature 145, and at armatures 143, 144, 115 120 125 130

and 146 connects up wipers 147, 148, and 150, respectively.

In the seized register set relay 362 energizes in response to the ground potential being placed on wiper 149, by armature 145 of switching relay 141, over a circuit which includes release trunk conductor 156 and armature 372 and its resting contact. Relay 362, upon energizing, opens a point in the circuit of release magnets 369 and 478 of the registers R and R', respectively, and places ground on locking conductor 399 at armature 375; opens a point in the circuit of busy relay 361 at armature 374; and at armature 373 connects up the lead from the common interrupter 372 for a purpose which will be explained subsequently.

When the calling subscriber operates his calling device in accordance with the first digit 3 in the number of the desired subscriber, the circuit of line relay 62 of the repeater F in the step by step office is interrupted three times. Each time line relay 62 deenergizes in response to one of these interruptions, it opens at armature 68 the circuit of line relay 102 of the trunk circuit TC in the panel office. As a further result of each deenergization of line relay 62 of the repeater F, it closes at armature 67 a circuit for relay 64 by way of armature 70 and its working contact. Relay 64 energizes in response to the first closure of its circuit and, being slow acting, retains its armature attracted throughout the series of impulses, and at armature 71 completes the bridge across conductors 72 and 73 by way of a direct path which excludes the right-hand repeating coil windings and the lower winding of electro-polarized relay 66. This is the usual expedient which is made use of in impulse repeaters to switch from a talking circuit to a dialling circuit.

In the panel office, line relay 102 of the trunk circuit TC, deenergizes in response to each of the above-named interruptions produced in its circuit by the line relay of the repeater F at the automatic office and, upon each deenergization, sends an impulse of current over operating conductor 155, at armature 112, by way of the working contact of armature 114 and said armature, armature 143 and its working contact, wiper 147, and bank contact 151. Each of the impulses in this series is transmitted from impulse conductor 155 to vertical magnet 370 of the register R, the first impulse of current being transmitted as follows: From ground by way of the previously traced circuit to impulse conductor 155 and thence by way of the resting contact of off normal spring 368 and said spring, relay 363, and vertical magnet 370 to battery. By the operation of vertical magnet 370, the switch wipers 431-436, inclusive, are raised step by step until they stand opposite the desired level of bank contacts, which in this case is the third. Relay 363 is ener-

gized in series with vertical magnet 370 and, being slow acting, retains its armature attracted throughout the series of impulses, thereby maintaining its own circuit and that of vertical magnet 370 intact after the off normal springs have shifted as they do upon the first vertical step. At the end of the series of impulses, relay 363 deenergizes and transfers the operating circuit from the vertical to the rotary magnet.

When the calling subscriber manipulates his calling device in accordance with the next digit 7 in the desired number, a corresponding number of impulses is sent over operating conductor 155 as before. Each of the seven impulses in this series is delivered to rotary magnet 371, the first impulse being delivered by way of the following circuit: From ground by way of the circuit as previously traced to operating conductor 155, and thence by way of the normally open contacts controlled by off normal spring 368, armature 376 and its resting contact, resting contact of armature 378 and said armature, relay 365, and rotary magnet 371 to battery. By the operation of rotary magnet 371, the wipers of the register R are rotated into engagement with the desired set of bank contacts in the third level, being the seventh set in this case. Relay 365 is energized in series with rotary magnet 371 and, being slow acting, retains its armature attracted throughout the rotary movement. Upon energizing, relay 365 places a shunt around armature 378 and its resting contact at armature 380 and at armature 381 closes a circuit for relay 364 from the grounded conductor 399. Relay 364, upon energizing, closes a locking circuit for itself at armature 379; prepares a circuit for vertical magnet 479 at armature 377; and at armature 378 opens a point in the circuit of rotary magnet 371 and relay 365, leaving the circuit established through armature 380 and its working contact. At the end of the rotary movement, relay 365 deenergizes and shifts the operating circuit from rotary magnet 371 to vertical magnet 479 of the register R' at armature 380.

When the next digit 3 in the desired subscriber's number is sent, the resulting train of impulses coming in over operating conductor 155 are sent to vertical magnet 479 of the register R', the first impulse being sent over the following circuit: From ground by way of the circuit as previously traced to armature 380 and thence by way of the resting contact of armature 380, working contact of armature 377 and said armature, contact of off normal spring 483 and said spring, series relay 473, and vertical magnet 479 to battery. By the operation of vertical magnet 479, the wipers 441-446, inclusive, of the register R' are raised opposite the desired level of bank contacts, which in this case is the third. Slow acting series relay 473 is

5 maintained energized during the vertical movement of the register R' and, like the corresponding relay 363 of the register R, maintains its own circuit and that of the associated vertical magnet intact after the off normal springs have shifted upon the first vertical step of the switch. At the end of the vertical movement of the register R', slow acting relay 473 deenergizes and transfers the operating circuit from the vertical magnet 479 to the rotary magnet 480.

10 When the train of impulses representing the next and last digit 7 in the desired subscriber's number is transmitted, rotary magnet 480 is energized a corresponding number of times, the first energization being effected over a circuit which extends from ground as previously traced to armature 377 and thence by way of the normally open contacts controlled by off normal spring 483, armature 484 and its resting contact, resting contact of armature 488 and said armature, relay 475, and rotary magnet 480 to battery. Slow acting series relay 475 is maintained energized during the rotary movement in series with rotary magnet 480. Upon energizing, relay 475 opens a point in the circuit of relay 476 and closes a circuit for relay 474 at armature 489 from grounded conductor 399. 15 Relay 474, upon energizing, locks itself to conductor 399 at armature 486, and prepares a circuit for relay 476 at armature 487. At the end of the rotary movement, relay 475 deenergizes and completes a circuit for relay 20 25 30 35 40 45 50 55 60 65 476 at armature 489. Relay 476, upon energizing, disconnects relay 475 and rotary magnet 480 at armature 488; removes ground from test conductor 425 and places ground on holding conductor 424 at armature 490; and at armature 491 places ground on the common start conductor 423.

Assuming the register allotter, Fig. 7, to be idle, start relay 429 is energized through the resting contact of armature 426' and said armature in response to the placing of ground on start conductor 423; closes a circuit for switching relay 430 and stepping magnet 428 in series at armature 448; and at armature 447 connects test wiper 438 to the junction of switching relay 430 and stepping magnet 428.

In case the wipers of the register allotter are standing on the bank contacts in which conductors 424-426, inclusive, terminate, switching relay 430 energizes immediately. 55 However, assuming the wipers to be standing on some other set of bank contacts, switching relay 430 is short circuited by the ground potential encountered by test wiper 438 and does not energize, and the wipers are rotated step by step in search of the waiting register set by stepping magnet 428, which operates in a buzzer-like manner from ground picked up by test wiper 438. When the set of contacts in which conductors 424-426, inclusive, terminate is reached, switching re-

lay 430, being no longer short circuited, energizes in series with stepping magnet 428. Stepping magnet 428, however, does not energize at this time on account of the high resistance of switching relay 430. Upon energizing, switching relay 430 locks itself to the grounded holding conductor 424 at armature 499; places ground on conductor 426 at armature 449' by way of armature 427 and its resting contact and wiper 440; and at armature 426' disconnects line relay 429 from the common start conductor 423, whereupon line relay 429 deenergizes.

70 In response to ground being placed on conductor 426, relay 428' energizes and connects conductors 411-422, inclusive, and 157 of the register set with the common conductors 451-458, inclusive, and 460-464, inclusive, respectively, of the transfer control circuit, Fig. 8. As a further result of the energization of relay 428', it places ground on conductor 459, whereupon relay 567 of the transfer control circuit, Fig. 8, energizes through the lower right-hand contact of sequence switch cam 582 and said cam, sequence switch 550 being in position 1 or position 10. The energization of relay 567, however, does not have any immediate effect. As a still further result of the energization of relay 428', it places ground on the conductor 158; thereby grounding assign conductor 129 of the incoming selector through bank contact 154 of the secondary switch SS, wiper 150, and the working contact of armature 146 and said armature. When this occurs, relay 106, in the trunk circuit TC, energizes and closes a locking circuit for its lower winding at armature 123, and at armature 122 removes ground from release conductor 127 of the incoming selector for a reason that will appear more fully hereinafter.

75 In the incoming selector, Fig. 4, in response to ground being placed on assign conductor 129 by way of a previously traced circuit, sequence switch 200 is moved out of position 1 upon its magnet being energized from assign conductor 129 and through the upper left-hand contact of cam 232 and said cam. Sequence switch 200 stops in position 2 to await the trunk finder, Fig. 9. In position 2, sequence switch 200 grounds the common start conductor 246 by way of the lower left-hand contact of cam 219 and said cam, armature 210 and its resting contact, and cam 225 and its lower left-hand contact. It will be noted that start conductor 246 traverses Figs. 3, 8, and 12, and from thence extends to all the finder selectors, such as the one shown in Fig. 9. Assuming the finder selector allotter to be in position 1, the sequence switch of finder selector No. 1, which is the one shown in Fig. 9, is in position 1 while the sequence switches of the other finder selectors are in other positions. With the assumption as noted, relay 617, Fig. 9, is energized 80 85 90 95 100 105 110 115 120 125 130

from ground on start conductor 246 through the lower left-hand contact of cam 543 and said cam, (sequence switch 600 being in position 1) the upper right-hand contact of cam 543, and relay 617 to battery. Upon energizing, relay 617 closes a locking circuit for itself at armature 626 as follows: from ground by way of commutator brush 663, commutator 665, upper left-hand contact of cam 635 and said cam, armature 626 and its working contact, and relay 617 to battery. As a further result of the energization of relay 617, it closes at armature 627 a circuit for the lower winding of relay 616 as follows: from ground by way of armature 627 and its working contact, upper right-hand contact of sequence switch cam 652 and said cam, upper left-hand contact of cam 652, and the lower winding of relay 616 to battery. Relay 616, upon energizing, closes a circuit for sequence switch 600 as follows: from ground by way of armature 625 and its working contact, upper right-hand contact of sequence switch cam 647 and said cam, and the magnet of sequence switch 600 to battery. When sequence switch 600 reaches position 1 $\frac{3}{4}$, the previously traced locking circuit for relay 617 is supplemented by one which is as follows: from ground by way of cam 640 and its upper left-hand contact, armature 621 and its resting contact, upper right-hand contact of cam 635 and said cam, armature 626 and its working contact, and relay 617 to battery. When sequence switch 600 reaches position 2, a circuit is closed for up-drive magnet 659 of the trunk finder as follows: from ground by way of armature 627 and its working contact, upper right-hand contact of cam 652, and up-drive magnet 659 to battery. In response to the energization of up-drive magnet 659, the elevator of the trunk finder is raised vertically and brushes 669—672, inclusive, are made to pass over their associated bank contacts in search of the trunk on which the call is waiting.

As a further result of the sequence switch 600 coming into position 2, a circuit is closed for up-drive magnet 601 of the sender selector as follows: from ground by way of armature 625 and its working contact, upper right-hand contact of sequence switch cam 642 and said cam, lower right-hand contact of cam 642, and up-drive magnet 601 to battery. Consequently, brushes 605—608, inclusive, of the sender selector are started upward in search of an idle sender at the same time that the brushes 669—673, inclusive, of the trunk finder are started upward in search of the waiting trunk. Although either of these two operations may be completed first, it will be assumed in the following description that the trunk finder finds the waiting trunk before the sender selector has found an idle sender. In any case, when the trunk finder has found the waiting trunk, sequence

switch 600 is moved out of position 2 and into position 3 and when the sender selector has selected an idle sender, sequence switch 600 is moved out of position 3 and into position 4, provided the sequence switch 600 has been moved into position 3 in response to the trunk finder finding the waiting trunk. 70

When the brushes 669—673, inclusive, of the trunk finder arrive upon the set of terminals in which conductors 247—251, inclusive, of the waiting trunk terminate, brush 670, upon making contact with its associated terminal in the above named set, closes a circuit for relay 615 as follows: from ground by way of the lower left-hand contact of sequence switch cam 221, Fig. 4, and said cam, upper right-hand contact of cam 221, (sequence switch 200 being in position 2) armature 211 and its resting contact, upper right-hand contact of cam 224 and said cam, lower right-hand contact of cam 224, conductor 250, brush 670, lower left-hand contact of sequence switch cam 636 and said cam, and relay 615 to battery. Relay 615, upon energizing, opens the second traced locking circuit of relay 617 at armature 621, leaving relay 617 energized by way of its locking circuit which includes strip 655 and commutator brush 663. When the brushes have become centered upon the contacts, brush 663 comes into engagement with an insulated portion of the strip 655, thereby opening the first locking circuit of relay 617, whereupon relay 617 deenergizes and opens the circuit of up-drive magnet 659 at armature 627. 90 When this occurs, the brushes of the trunk finder stop. As a further result of the energization of relay 615, it closes a locking circuit for itself at armature 621 as follows: from ground by way of cam 640 and its upper left-hand contact, armature 621 and its working contact, upper left-hand contact of cam 636 and said cam, and relay 615 to battery. As a still further result of the energization of relay 615, it closes a circuit for relay 614 at armature 622 by way of resistance 630. Relay 614, upon energizing, connects up wiper 669 at armature 619; connects up wiper 671 at armature 618; and at armature 620 connects up wiper 673, thereby completing the holding circuit for relay 615 as follows: from ground by way of the lower left-hand contact of cam 221 and said cam, upper right-hand contact of cam 221, armature 211 and its resting contact, upper right-hand contact of cam 224 and said cam, upper left-hand contact of cam 224, holding conductor 247, brush 673, armature 620 and its working contact, armature 621 and its working contact, upper left-hand contact of cam 636 and said cam, and relay 615 to battery. The closure of its locking circuit enables relay 615 to remain energized after its first traced locking circuit has been opened at cam 640 upon sequence switch 600 moving 95 100 105 110 115 120 125 130

beyond position 3. Relay 617, in addition to opening the circuit of up-drive magnet 659, as described, upon falling back, closes a circuit for sequence switch 600 as follows: 5 from ground by way of armature 627 and its resting contact, upper right-hand contact of cam 650 and said cam, and the magnet of sequence switch 600 to battery. The sequence switch 600 now moves from position 10 2 into position 3 to wait until the operation of the sender selector is completed.

The operation of the sender selector will now be taken up. With the sequences switch 600 in position 2 or position 3, it will be noted 15 that relay 616, which relay energized initially upon the energization of relay 617, as described, is energized through a commutator brush 610 of the sender selector over a circuit which extends as follows: from ground 20 by way of cam 641 and its upper right-hand contact, working contact of armature 623 and said armature, cam 644, and its upper right-hand contact, commutator brush 610, strip 612, upper right-hand contact of cam 25 639 and said cam, and the upper winding of relay 616 to battery. When commutator brush 610 reaches the first insulated segment of the commutator 612, the brushes 605—608, inclusive, are in engagement with the first 30 set of terminals and, assuming the sender terminating in those terminals to be busy, relay 616 is held energized by its lower winding over the following circuit: from ground encountered by brush 607, lower right-hand contact of cam 645 and said cam, lower left-hand contact of cam 645, armature 624 and its working contact, cam 648 and its lower left-hand contact, and the lower winding of relay 616 to battery. Consequently, the up- 35 drive movement continues until an idle sender is found, which sender, it will be assumed, is the one shown in Figs. 10 and 11. When the terminals of said idle sender is reached, commutator brush 610 is in engagement with an 40 insulated segment, and, consequently, the circuit for the upper winding or relay 616 is opened. Also, since the sender shown in Figs. 10 and 11 is idle, test conductor 752 is not grounded and no circuit is closed for the 45 lower winding of relay 616 and relay 616 de-energizes and opens the circuit of up-drive magnet 601 at armature 625, at the same time closing a circuit for sequence switch 600 as follows: from ground by way of armature 50 625 and its resting contact, upper left-hand contact of cam 647 and said cam, and the magnet of sequence switch 600 to battery. Sequence switch 600 now moves from position 55 3 into position 4.

60 With sequence switch 600 in position 4, a circuit is closed for relay 712 of the selected sender, (Fig. 10) as follows: from ground by way of armature 629 of relay 614 of the finder selector, Fig. 9, and its working contact, up- 65 per left-hand contact of sequence switch cam

649 and said cam, lower right-hand contact of cam 649, brush 605, conductor 750, cam 703 and its lower left-hand contact, (sequence switch 700 being in position 1) and the upper winding of relay 712 to battery. Relay 712, 70 upon energizing, closes a circuit for sequence switch 700 at armature 717 by way of the lower left-hand contact of cam 704 and said cam. Sequence switch 700 now moves from position 1 to position 2. As a further result of the energization of relay 712, it closes a locking circuit for itself at armature 716 as follows: from ground by way of the upper left-hand contact of cam 645, Fig. 9, and said cam, lower right-hand contact of cam 645, brush 80 607, conductor 752, armature 716 and its working contact, and relay 712 to battery. When sequence switch 700 reaches position 2, the lower winding of relay 712 is connected up at its lower terminal by cam 702. This, 85 however, does not have any effect for the time being.

Returning now to the finder selector link, Fig. 9, as a further result of sequence switch 600 moving into position 4, relay 616 energizes again over the following circuit: from ground by way of the upper right-hand contact of cam 226, Fig. 4, and said cam, lower left-hand contact of cam 226, conductor 249, brush 671, working contact of armature 618 90 and said armature, upper left-hand contact of cam 639 and said cam, and the upper winding of relay 616 to battery. Upon energizing, relay 616 closes a circuit for sequence switch 600 as follows: from ground by way 95 of armature 625 and its working contact, upper right-hand contact of cam 647 and said cam, and the magnet of sequence switch 600 to battery. Sequence switch 600 now moves from position 4 to position 5.

When sequence switch 600 comes into position 5, a circuit is closed for sequence switch 200 of the incoming selector, Fig. 4, as follows: from ground by way of armature 572 of relay 567, Fig. 8, and its working contact, lower left-hand contact of sequence switch cam 580 and said cam, armature 575 and its resting contact, upper right-hand contact of cam 593 and said cam, lower left-hand contact of cam 593, conductor 857, cam 853 of the allotter sequence switch 850, Fig. 12, and its lower right-hand contact, conductor 865, lower left-hand contact of cam 642 of sequence switch 600, Fig. 9, and said cam, upper left-hand contact of cam 642, working contact of armature 619 and said armature, brush 669, conductor 251, lower right-hand contact of cam 229 and said cam, (Fig. 4) and the magnet of sequence switch 200 to battery.

Sequence switch 200 now advances from position 2 to position 3, whereupon cam 226 opens at its upper right-hand contact with circuit of relay 616, Fig. 9. Relay 616, upon deenergizing, closes a circuit for sequence 130

switch 600 as follows: from ground by way of armature 625 and its resting contact, upper left-hand contact of cam 647 and said cam, and the magnet of sequence switch 600 to battery.

Sequence switch 600 now advances from position 5 to position 6, whereupon a circuit is closed for relay 655 of the finder selector in series with relay 570 of the transfer control circuit, Fig. 8. As intimated before, sequence switch 550 of the transfer control circuit has two normal positions and, consequently, may be standing in either of the two normal positions, which are positions 1 and 10. For the sake of illustration, it will be assumed that sequence switch 550 is standing in position 1 at this time. The above mentioned circuit for relays 655 and 570 in series is as follows: from ground by way of armature 629 of relay 614 and its working contact, upper left-hand contact of cam 649 and said cam, lower left-hand contact of cam 649, relay 655, conductor 466, lower right-hand contact of cam 587 and said cam, upper right-hand contact of cam 587, and the lower winding of relay 570 to battery.

Relay 655, Fig. 9, upon energizing over the above traced circuit, connects brushes 605 and 606 with conductors 468 and 467 at armatures 658 and 657, respectively. As a further result of the energization of relay 655, it closes a circuit for relay 616 as follows: from ground by way of the working contact of armature 656 and said armature, lower right-hand contact of cam 652 and said cam, upper left-hand contact of cam 652, and the lower winding of relay 616 to battery. Relay 616, upon energizing, connects brush 608 with conductor 465 of the transfer control circuit at armature 624 by way of the upper right-hand contact of cam 646 and said cam, upper left-hand contact of cam 646, armature 624 and its working contact, and cam 648 and its upper right-hand contact. This completes the connecting of the conductors 465, 467, and 468 of the common transfer control circuit to the corresponding conductors 753, 751, and 750, respectively, in preparation for the transferring of the stored number to the waiting sender. As a further result of the energization of relay 616, it closes a circuit for sequence switch 600 at armature 625 by way of the upper right-hand contact of cam 647 and said cam. When this occurs, sequence switch 600 moves from position 6 to position 7, whereupon the circuit of relays 570 and 655 is shifted so as to include the lower right-hand contact of cam 644 and said cam, armature 623 and its working contact, upper right-hand contact of cam 649 and said cam instead of the lower left-hand contact of cam 649.

As a further result of the sequence switch 600 moving into position 7, or to be more explicit, when the said sequence switch

reaches position 6 3/4, a circuit is closed for sequence switch 850, Fig. 12, as follows: from ground by way of cam 640 and its lower left-hand contact, conductor 866, lower right-hand contact of cam 855, Fig. 12, and said cam, and the magnet of sequence switch 850 to battery. Sequence switch 850 now advances from position 1 into position 2, thereby assigning finder selector No. 2 in case said finder selector is idle.

In the transfer control switch, Fig. 8, relay 570, upon energizing in series with relay 655, Fig. 9, as pointed out above, closes a locking circuit for its upper winding at armature 557 as follows: from ground by way of armature 572 and its working contact, lower left-hand contact of cam 580 and said cam, lower right-hand contact of cam 580, armature 557 and its working contact, and the upper winding of relay 570 to battery. As a further result of the energization of relay 570, it places a shunt around cam 587 and its upper right-hand contact at armature 576 so as to maintain the circuit of its own lower winding and of relay 655, Fig. 9, intact after the upper right-hand contact of sequence switch cam 587 has opened upon sequence switch 550 moving out of position 1. As a still further result of the energization of relay 570, it closes a circuit for sequence switch 550 as follows: from ground by way of armature 572 and its working contact, lower left-hand contact of cam 580 and said cam, armature 575 and its working contact, lower left-hand contact of cam 579 and said cam, and the magnet of sequence switch 550 to battery. Sequence switch 550 now advances from position 1 to position 2, whereupon the thousands registration is transferred to the sender.

Before describing in detail how the registered number is transferred, the method used in transferring the number will be considered briefly. As explained hereinbefore, the three conductors 465, 467, and 468 of the transfer control circuit are connected through to the corresponding conductors 753, 751, and 750, respectively, of the sender, Fig. 10. In the sender, these conductors are at this time connected to the thousands set of set-up relays comprising the four relays 811-814, inclusive. These four relays are pulled up or left normal in any one of ten different combinations, depending upon the way in which the three control conductors are connected up in response to the thousands registration of the register R, Fig. 6. After the thousands registration is transferred, the hundreds registration is transferred to the set of hundreds relays comprising relays 821-824, inclusive. In the same manner, the tens and then the units registration is transferred.

The detailed description of the transferring of the number will now be given. When sequence switch 550 of the transfer control

circuit, Fig. 8, moves into position 2, as hereinbefore described, relay 569 of the transfer control circuit and relay 813 of the sender, Fig. 11, energize in series over the following circuit: from ground by way of the right-hand winding of relay 813, right-hand winding of relay 811, conductor 761, upper left-hand contact of cam 710 and said cam, conductor 750, brush 605 of the sender selector, armature 658 and its working contact, conductor 468, lower right-hand contact of cam 598 and said cam, cam 590 and its upper left-hand contact, conductor 460, a contact and associated armature of relay 428', conductor 419, wiper 435, the seventh contact in the third level of the associated bank, conductor 404, lower left-hand contact of cam 589 and said cam, upper right-hand contact of cam 589, upper and lower windings of relay 569 in series, and the upper right-hand contact of cam 584 and said cam to battery. Relay 813, Fig. 11, upon energizing over this circuit, closes a locking circuit for itself at its left-hand armature. Relay 811 which is included in the above traced circuit, is marginally adjusted and does not energize at this time on account of the high resistance of the upper winding of relay 569, Fig. 8. The marginal adjustment of relay 811 as well as the marginal adjustment of the various other marginal relays of the sender, it may be stated, is denoted by the letters MG.

Relay 569, upon energizing, places a shunt around resistance 472 at armature 574 so as to allow relay 814 of the sender to energize when its circuit is closed.

As a further result of sequence switch 550 moving into position 2, relay 553 of the transfer control circuit, Fig. 8, and relay 812 of the sender, Fig. 11, energize in series over the following circuit: from ground by way of the resting contact of armature 562 of relay 554, Fig. 8, and said armature, upper winding of relay 553, cam 583 and its lower right-hand contact, conductor 461, a contact and associated armature of relay 428', conductor 420, wiper 436 of the register R, seventh contact in the third level of the bank of wiper 436, conductor 403, lower left-hand contact of sequence switch cam 591, Fig. 8, and said cam, conductor 467, armature 657 and its working contact, brush 606, conductor 751, cam 706 and its upper right-hand contact, cam 711 and its upper left-hand contact, conductor 771, and the right-hand winding of relay 812 to battery. Relay 812, upon energizing, closes a locking circuit for itself at its left-hand armature. Relay 553 of the transfer control circuit, Fig. 8, upon energizing over the above traced circuit, closes a locking circuit for itself at armature 561, and at the normally closed contacts controlled by armature 561 removes a shunt from around relay 554, whereupon relay 554 energizes through the lower right-hand contact of cam 578 and said cam and resistance 474; opens the initial circuit of relay 553 at armature 562, leaving relay 553 locked up at armature 561; and at armature 563 opens another point in its previously established shunt and prepares a circuit for the associated sequence switch 550. As a further result of the energization of relay 553, it completes a circuit for relays 714 and 814 of the sender in series as follows: from ground by way of the upper winding of relay 714, Fig. 10, lower right-hand contact of cam 733 and said cam, cam 707 and its lower left-hand contact, conductor 784, right-hand winding of relay 814, conductor 753, brush 608 of the sender selector, upper right-hand contact of cam 646 and said cam, upper left-hand contact of cam 646, armature 624 and its working contact, cam 648 and its upper right-hand contact, conductor 465, cam 481 and its lower right-hand contact, armature 574 and its working contact, armature 565 and its working contact, resistance 473, and the lower right-hand contact of cam 584 and said cam to battery. Relay 814 of the sender, upon energizing, closes a locking circuit for itself at its right-hand armature.

Relay 714, Fig. 10, upon energizing, closes a circuit for sequence switch 700 at armature 719, whereupon sequence switch 700 moves from position 2 into position 3 for the hundreds registration. Relay 714 deenergizes when sequence switch 700 leaves position 2, upon its circuit being opened at the lower left-hand contact of cam 707, and sequence switch 700 is carried the remaining distance to position 3 by its local contact in the usual manner. As a further result of sequence switch 700 moving from position 2 into position 3, it opens at the upper left-hand contact of cam 711 the circuit of relay 553, Fig. 8. Relay 553, upon deenergizing, closes at the normally closed contacts controlled by armature 561 a circuit for sequence switch 550 by way of armature 563 and its working contact, and the lower right-hand contact of cam 577 and said cam. Sequence switch 550 now moves from position 2 to position 3, whereupon relay 554 deenergizes due to its circuit being opened at the lower right-hand contact of cam 578. The thousands registration has been transferred and the thousands relays 812-814, inclusive, have been energized as pointed out above.

The transfer of the hundreds digit is now accomplished according to the following explanation. With sequence switch 550 of the transfer control circuit in position 3, relay 568 energizes over the following circuit: from ground by way of cam 585 and its lower right-hand contact, conductor 455, a contact and associated armature of relay 428', conductor 415, wiper 433, the seventh contact in the third level of the bank of wiper 130

433, conductor 406, lower right-hand contact of cam 586 and said cam, upper right-hand contact of cam 586, upper and lower windings of relay 568 in series, and the upper left-hand contact of cam 584 and said cam to battery. Relay 568, upon energizing, places a shunt around resistance 472 at armature 573 so as to allow relay 824 of the sender to energize when its circuit is closed.

10 As a further result of sequence switch 550 moving into position 3, relay 552 energizes in series with relay 822, Fig. 11, over the following circuit: from ground by way of the resting contact of armature 559 of relay 561, Fig. 8, and said armature, upper winding of relay 552, cam 595 and its upper left-hand contact, conductor 452, a contact and associated armature of relay 428', conductor 412, wiper 432, the seventh contact in the third level of the bank of wiper 432, conductor 403, lower left-hand contact of cam 590 and said cam, cam 593 and its lower right-hand contact, conductor 468, previously traced circuit to conductor 750, Fig. 10, cam 710 and its upper right-hand contact, conductor 762, and the right-hand winding of relay 822 to battery. Relay 822, upon energizing, closes a locking circuit for itself at its left-hand armature. Relay 552, Fig. 8, upon energizing over the above traced circuit, closes a locking circuit for itself at armature 560, and at the normally closed contacts controlled by armature 560 removes a shunt from around relay 551 and allows it to energize in series with the lower left-hand contact of cam 578 and said cam and resistance 474. Upon energizing, relay 551 opens the initial circuit of relay 552 at armature 559, leaving relay 552 locked up through armature 560 and its working contact, and at armature 558 opens a further point in its previously closed shunt and prepares a circuit for moving sequence switch 550 out of position 3. As a further result of the above mentioned energization of relay 552, it closes at armature 564 a circuit for relays 714 and 824 of the sender, Figs. 10 and 11, as follows: from ground by way of cam 588 and its upper left-hand contact, resistance 475, working contact of armature 564 and said armature, working contact of armature 573 of relay 568 and said armature, lower left-hand contact of cam 481 and said cam, conductor 465, previously traced circuit to conductor 753, Figs. 10 and 11, right-hand winding of relay 824, conductor 783, lower left-hand contact of cam 707 and said cam, cam 733 and its upper contact, and the lower winding of relay 714 to battery. Relay 824, upon energizing, closes a locking circuit for itself at its left-hand armature, and relay 714, upon energizing, advances sequence switch 700 from position 3 to position 4 in the usual manner. Relay 714 energizes as a result of its circuit being

opened at cam 733 when sequence switch 700 moves out of position 3. As a further result of sequence switch 700 moving out of position 3, it opens at armature 710 and its upper right-hand contact the circuit of relay 552, Fig. 8. Relay 552, upon deenergizing, completes at the normally closed contacts controlled by armature 560, a circuit for driving sequence switch 550 out of position 3 and into position 4. This circuit includes armature 558 and its working contact, and the lower left-hand contact of cam 577 and said cam. Sequence switch 550 now moves from position 3 to position 4 and relay 551 deenergizes in response to the opening of its circuit at the lower left-hand contact of cam 578.

The hundreds registration has now been transferred and the transfer of the tens registration takes place. With sequence switch 550 in position 4, relays 831 and 833, Fig. 11, energize over the following circuit: from ground by way of the right-hand winding of relay 833, right-hand winding of relay 831, conductor 763, lower right-hand contact of cam 710 and said cam, previously traced circuit to conductor 468, Fig. 8, lower right-hand contact of cam 593 and said cam, cam 590 and its upper right-hand contact, conductor 462, a contact and associated armature of relay 428', conductor 421, wiper 445 of the register R', seventh contact in the third level in the bank of wiper 445, conductor 402, lower right-hand contact of cam 594 and said cam, and resistance 555 to battery. Relays 831 and 833, upon energizing, close locking circuits for themselves at their respective left-hand armatures. As a further result of sequence switch 550, Fig. 8, moving into position 4, relay 553 of the transfer control circuit and relay 832, Fig. 11, operate in series over the following circuit: from ground by way of the resting contact of armature 562, Fig. 8, and said armature, upper winding of relay 553, cam 583 and its lower left-hand contact, conductor 463, a contact and the associated armature of relay 428', conductor 422, wiper 446 of the register R', the seventh contact in the third level of the bank of wiper 446, conductor 408, lower right-hand contact of cam 592 and said cam, conductor 467, previously traced circuit to cam 711, Fig. 10, lower right-hand contact of cam 711, conductor 773, and the right-hand winding of relay 832 to battery. Relay 832, upon energizing, closes a locking circuit for itself at its left-hand armature. Relay 553, Fig. 8, upon energizing over the above traced circuit, closes a locking circuit for itself at armature 561 and at the normally closed contacts controlled by armature 561, removes a shunt from around relay 554, whereupon relay 554 energizes with the results hereinbefore described. As a further result of the energization of relay 553, it completes at armature 565 a cir-

cuit through relays 714 and 834, Figs. 10 and 11, respectively, as follows: from ground by way of the upper winding of relay 714, Fig. 10, lower right-hand contact of cam 733 and said cam, cam 707 and its upper right-hand contact, conductor 782, right-hand winding of relay 834, conductor 753, previously traced circuit to conductor 465, Fig. 8, cam 481 and its upper left-hand contact, 10 resistance 472, armature 565 and its working contact, resistance 473, and the lower right-hand contact of cam 584 and said cam to battery. Relay 714, Fig. 10, energizes over the above traced circuit, but relay 834, Fig. 11, being marginally adjusted, does not energize on account of resistances 472 and 473, Fig. 8. Relay 714, upon energizing, advances sequence switch 700 from position 4 into position 5 in the usual manner. Relay 714 de- 20 energizes in response to the circuit being opened at the lower contact of cam 707 when the sequence switch leaves position 4. As a further result of sequence switch 700 moving into position 5, it opens at cam 711 and its lower right-hand contact the circuit of relay 553, Fig. 8. Relay 553, upon deenergizing, advances sequence switch 550 out of position 4 and into position 5 in the hereinbefore de- 30 scribed manner, whereupon relay 554 deenergizes owing to its circuit being opened at the lower right-hand contact of cam 578.

The transfer of the tens registration is now complete and the transfer of the units registration now takes place. With sequence switch 550 in position 5, relay 568 energizes over the following circuit: from ground by way of cam 485 and its lower left-hand contact, conductor 457, a contact and associated armature of relay 428', conductor 417, wiper 443, the seventh contact in the third level of the bank of wiper 443, conductor 406, lower right-hand contact of cam 586 and said cam, upper right-hand contact of cam 586, upper and lower windings of relay 568 in series, 40 and the upper left-hand contact of cam 584 and said cam to battery. Relay 568, upon energizing, shunts resistance 472 so as to allow relay 844, Fig. 11, to energize when its circuit is closed. As a further result of sequence switch 850 moving into position 5, relay 552, Fig. 8, energizes in series with relay 842, Fig. 11, over the following circuit: from ground by way of the resting contact of armature 559 and said armature, upper winding of relay 552, cam 495 and its upper right-hand contact, conductor 454, a contact and associated armature of relay 428', conductor 414, wiper 442, seventh contact in the third level of the bank of wiper 442, conductor 408, 50 upper left-hand contact of cam 593 and said cam, lower right-hand contact of cam 593, conductor 468, previously traced circuit to conductor 750, Fig. 10, cam 710 and its lower left-hand contact, conductor 764 and the 60 right-hand winding of relay 842 to battery. 65 Relay 842, upon energizing, closes a locking circuit for its left-hand winding at its left-hand armature. Upon energizing, relay 552 closes a locking circuit for itself and removes a shunt from around relay 551 at armature 560, whereupon relay 551 energizes with the hereinbefore described results: As a further result of the energization of relay 552, Fig. 8, it completes at armature 564 the following circuit for relays 714 and 844, Figs. 10 and 11, respectively: from ground by way of cam 588 and its upper left-hand contact, resistance 475, working contact of armature 564 and said armature, working contact of armature 573 and said armature, lower left-hand contact of cam 481 and said cam, conductor 465, previously traced circuit to conductor 753, Figs. 10 and 11, right-hand winding of relay 844, conductor 781, upper left-hand contact of cam 707 and said cam, cam 733 and its upper contact, and the lower winding of relay 714 to battery. Relay 844, upon energizing, closes a locking circuit for itself at its left-hand armature, and relay 714, upon energizing, advances sequences switch 700 from position 5 to position 6 and then deenergizes in response to the opening of its circuit at the upper contact of cam 733. It may be stated that sequence switch 700 is now in position to control the brush selection of the incoming selector, Fig. 4, and does not advance again until that operation is completed.

As a further result of sequence switch 700 passing out of position 5, it opens the circuit of relay 552, Fig. 8, at the lower left-hand contact of cam 710, whereupon relay 552 deenergizes and closes at the normally closed contacts controlled by armature 560 a circuit for sequence switch 550 by way of armature 558 and its working contact and the lower left-hand contact of cam 577 and said cam. When this occurs, sequence switch 550 advances from position 5 to position 6.

The complete registration has been transferred to the sender, and the release of the registers R and R' and the setting of the panel switches next takes place, as will be now explained. With sequence switch 550 in position 6, battery is placed on conductor 464 by cam 589 and relay 566 is energized over the following circuit: from ground by way of relay 566, resistance 469, upper left-hand contact of cam 589 and said cam, and the lower right-hand contact of cam 589 to battery. Relay 566, upon energizing, places battery upon conductor 464 independent of cam 589 at armature 571. As a further result of battery being placed on conductor 464, a circuit is closed for relay 104 of the trunk circuit TC, Fig. 2, as follows: from ground by way of the upper winding of relay 104, armature 144 and its working contact, wiper 148, bank contact 152, conductor 157, an armature and the associated contact of relay 428', Fig. 7, and conductor 464 to battery. 130

Relay 104, upon energizing, opens a point in the test circuit of the secondary switch SS at armature 118; prepares a circuit for relay 105 at armature 116; and at armature 5 117 opens the circuit of switching relay 141 of the secondary switch SS and closes a locking circuit for its own lower winding. Switching relay 141 now deenergizes and disconnects the wipers of the secondary switch 10 SS, leaving relay 104 locked up through its lower winding. In the register set, Fig. 6, release relay 362 deenergizes in response to the above described operation of relay 104, Fig. 2, and closes a circuit for relay 361 at 15 armature 374. This circuit includes off normal contacts 366 of the register R and off normal contacts 481 of the register R' in multiple. Relay 361, upon energizing, renders the register set non-selectable by grounding 20 conductor 156 at armature 372. As a further result of the deenergization of relay 362, it disconnects the common interrupter at armature 373, and at armature 375 opens the circuit of relays 364 and 476 of the registers R 25 and R', respectively. The wipers of the registers R and R' are now restored to normal position in the usual manner upon the energization of their respective release magnets. The circuits of release magnets 369 and 478 30 are opened at off normal contacts 367—482, respectively, when the respective switch shafts have been restored to normal. As a further result of the shafts of the two switches reaching normal position, the circuit of busying relay 361 is opened at off normal contacts 366 and 481, whereupon relay 361 deenergizes and renders the register set 35 selectable.

As a result of the deenergization of relay 40 476 of the register R' as pointed out above, ground is removed from the common start conductor 423 at armature 491, and ground is removed from holding conductor 424 at armature 490, whereupon switching relay 430 45 of the register allotter deenergizes. As a still further result of the deenergization of relay 476, ground is replaced on conductor 425 at armature 490, so as to cause the wipers of the register allotter to pass over the contacts of the register set shown until such register set is in position to be allotted again.

As a still further result of battery being placed on conductor 464, Fig. 7, by sequence switch cam 589, Fig. 8, cut-off relay 437 of 55 the register allotter energizes and opens the circuit of relay 428' at armature 427. Relay 428' thereupon deenergizes with results that are apparent. In response to the removal of the ground potential from conductor 459 by 60 relay 428', relay 567, Fig. 8, deenergizes and closes a circuit for sequence switch 550 as follows: from ground by way of armature 572 and its resting contact, upper left-hand contact of cam 579 and said cam, and the magnet of sequence switch 550 to battery. Se-

quence switch 550 now moves from position 6 and is driven to position 10 by its local contact.

When sequence switch 550 has moved as far as position 8, relay 566 is short circuited provided a finder selector is available and has been allotted by the finder selector allotter, Fig. 12. Assuming the finder selector No. 2 is the one allotted, said finder selector is in position No. 2, which is the waiting position, 70 and conductor 858 is grounded by the sequence switch of finder selector No. 2 by the cam and contact which correspond to cam 641, Fig. 9, and its lower left-hand contact. That being the case, the ground potential on conductor 858 extends by way of the lower left-hand contact of cam 586, Fig. 8, and said cam, and the upper left-hand contact of cam 586 to the junction of relay 566 and resistance 469. Consequently, relay 566, being short 75 circuited, deenergizes and at armature 571 opens the circuit of relay 437, Fig. 7. Relay 437, upon deenergizing, connects up wiper 440 again so as to render the register allotter 80 operative to allot the next register that becomes ready.

Returning now to the point in the operation of the transfer control circuit, Fig. 8, at which sequence switch 550 moves from position 5 into position 6, upon the completion of 95 the transfer of the units digit 7, as above described, the circuit of relay 570 of the transfer control circuit and of relay 655 of the finder selector, Fig. 9, is opened at cam 587, Fig. 8, and its lower left-hand contact when 100 sequence switch 550 moves out of position 5. The deenergization of relay 570 does not produce any particular effect at this time. Relay 655, Fig. 9, upon deenergizing, disconnects 105 conductors 467 and 468 of the transfer control circuit from the corresponding brushes of the sender selector at armatures 657 and 658 and at armature 656 opens the circuit of the lower winding of relay 616. Relay 616, upon deenergizing, disconnects conductor 465 110 from brush 608 at armature 624, and closes a circuit for sequence switch 600 at armature 625 as follows: from ground by way of armature 625 and its resting contact, upper left-hand contact of cam 647 and said cam, and the magnet of sequence switch 600 to battery. Sequence switch 600 now moves from 115 position 7 to position 8, thereby closing through at cam 637 the fundamental circuit from the incoming selector, Fig. 4, to the 120 sender, Figs. 10 and 11.

In response to the above mentioned closure of the fundamental circuit, relay 713 of the sender, Fig. 10, energizes in series with the lower winding of relay 204 of the incoming 125 selector, Fig. 4, over the following circuit: from ground by way of armature 732 of counting relay 720, Fig. 10, and its resting contact, relay 713, lower right-hand contact of cam 703 and said cam, conductor 750, 130

brush 605, of the sender selector, lower right-hand contact of cam 637 and said cam, upper right-hand contact of cam 637, armature 618 and its working contact, brush 671 of the 5 trunk finder, conductor 249, lower right-hand contact of cam 223 and said cam (sequence switch 200 being in position 3), cam 222 and its upper right-hand contact, and the lower winding of relay 204 to battery. Relay 713 10 of the sender, upon energizing, closes a circuit for the upper winding of relay 721 as follows: from ground by way of the working contact of armature 718 and said armature, cam 705 and its lower left-hand contact, conductor 15 766, right-hand armature of relay 813 and its working contact (relays 813 and 812 having been energized as described hereinbefore), middle armature of relay 812 and its working contact, middle armature of relay 811 20 and its resting contact, conductor 741, upper armature of relay 721 and its resting contact, and the upper winding of relay 721 to battery. Relay 721, being marginally adjusted, energizes at this time far enough to operate its 25 lightly adjusted lower armature, but not far enough to operate its upper armature. This adjustment is made easy owing to the fact that the upper winding of relay 721 is composed of a relatively small number of turns 30 of wire having a comparatively high resistance. The lower armature of relay 721, upon coming into engagement with its associated contact, closes a locking circuit for relay 721 through its lower winding. This locking circuit does not come into use for the time being, 35 however, owing to the fact that the lower winding is grounded at both terminals.

In the incoming selector, relay 204, upon energizing in series with relay 713 of the 40 sender over the above traced fundamental circuit, drives sequence switch 200 from position 3 at armature 210, the circuit being as follows: from ground by way of the lower left-hand contact of cam 219 and said cam, armature 210 and its working contact, lower right-hand contact of cam 232 and said cam, and the magnet of sequence switch 200 to battery. Sequence switch 200 is driven through position 45 105 and into position 5 by its local contact which does not open in position 4. When sequence switch 200 leaves position 4, a point in the initial path of the fundamental circuit is opened at cam 222 and its upper right-hand contact. However, due to the energization 50 of relay 204, the fundamental circuit remains closed through the upper right-hand contact of cam 223, working contact of armature 211 and said armature, upper right-hand contact of cam 221 and said cam, and the lower right-hand contact of cam 221.

When sequence switch 200 arrives in position 5, a circuit is closed for up-drive magnet 213 at the lower left-hand contact of cam 233 as follows: from ground by way of the lower 55 left-hand contact of cam 219 and said cam,

armature 210 and its working contact, upper right-hand contact of cam 233 and said cam, lower left-hand contact of cam 233, and up-drive magnet 213 to battery. Up-drive magnet 213, upon energizing, presses the steel 70 tape of the elevator against the constantly rotating shaft 215, whereupon the elevator moves upward in the usual manner.

The first selection to be made is a choice 75 between the five sets of brushes of the selector which are numbered 0, 1, 2, 3, 4, respectively. The setting of the thousands relays, Fig. 11, has predetermined that the set of brushes to be tripped in this case is set No. 1, which we will assume is the set comprising brushes 80 252-254, inclusive.

When commutator brush 238 comes into engagement with the first conducting segment 85 on strip 243, ground is placed on fundamental conductor 249 by way of the following circuit: from ground by way of cam 234 and its upper right-hand contact, brush 238, strip 243, lower left-hand contact of cam 222 and said cam, and cam 233 and its lower left-hand contact. This ground on conductor 249 short circuits relay 713 of the sender, Fig. 10, 90 and allows it to deenergize. Upon deenergizing, relay 713 opens the initial circuit of relay 721 at armature 718, whereupon relay 721 pulls all the way up over its locking circuit which now includes its two windings in series, and at its upper armature disconnects conductor 741 from the junction of its own windings and extends it to the corresponding 95 point of relay 720.

When brush 238 of the incoming selector, Fig. 4, comes into engagement with the first insulated segment of strip 243, which is the position in which it stops when the "0" brush 100 is to be tripped, the shunt is removed from around relay 713 of the sender, whereupon relay 713 energizes and closes a circuit for the upper winding of relay 720 at armature 718. This circuit extends as previously traced to conductor 741 and thence by way of the upper armature of relay 721 and its working contact, upper armature of relay 720 and its resting contact, and the upper winding of relay 720 to battery. Relay 720, being designed and adjusted similar to relay 721, 110 pulls up just far enough to bring armature 731 into engagement with its associated contact.

When brush 238 of the incoming selector comes into engagement with the second conducting segment of strip 243, it again short circuits relay 713 of the sender, whereupon relay 713 deenergizes and opens the initial circuit of relay 720. When this occurs, relay 720 pulls all the way up through its two windings in series; disconnects relay 713 at armature 732, thereby opening a point in the fundamental circuit; and at armature 732 closes a circuit for driving sequence switch 700 from position 6 to position 7. Sequence 120 125 130

switch 700 is driven from position 7 to position 8 by its local contact which does not open in position 7.

In the incoming selector, brush 238 passes off the second conducting segment and opens the circuit of relay 204 (the fundamental circuit having been opened in the sender), at about the same time that sequence switch 700 of the sender, Fig. 10, moves out of position 6, as described above. Relay 204, upon deenergizing, opens up the fundamental circuit at armature 211 so as to prevent the fundamental circuit from being re-established by the sender before the incoming selector is ready for the next operation. As a further result of the deenergization of relay 204, the circuit of up-drive magnet 213 is opened at armature 210, and a circuit for sequence switch 200 is closed by armature 210 by way of the lower left-hand contact of cam 232 and said cam. The elevator now stops due to the deenergization of up-drive magnet 213 and sequence switch 200 is driven out of position 5 and into position 6 in response to the above named closure of its circuit.

Returning now to the sender, Fig. 10, when sequence switch 700 leaves position 6, as it is being driven from position 6 to position 8, as described above, it opens the locking circuit of relays 720 and 721 at sequence switch cam 701, whereupon relays 720 and 721 deenergize. Relay 720, upon deenergizing, prepares the fundamental circuit again at armature 732. When sequence switch 700 reaches position 8, a further point in the fundamental circuit is closed at the lower right-hand contact of sequence switch cam 703.

In the incoming selector, when sequence switch 200 reaches position 6, the fundamental circuit is again established at cam 222 and its upper right-hand contact, and a circuit is closed for trip magnet 212 by way of cam 234 and its lower right-hand contact. Trip magnet 212 accordingly energizes in readiness for tripping the No. 1 set of brushes when the elevator starts up the next time. In the sender, relay 713 now energizes in series with relay 204 of the incoming selector over the previously traced fundamental circuit, and closes at armature 718 a circuit for counting relay 723 as follows: from ground by way of the working contact of armature 718 and said armature, cam 705 and its lower right-hand contact, conductor 767, right-hand armature of relay 814 and its working contact, (relays 814 and 824 having been energized to predetermine the group selection as hereinbefore described) middle armature of relay 824 and its working contact, conductor 743, upper armature of relay 723 and its resting contact, and the upper winding of relay 723 to battery. Relay 723, being of the same design and adjustment as are the other counting relays of the

sender, energizes only part way and brings its lower armature into engagement with its associated contact.

The incoming group selection now takes place as will be pointed out. In the incoming selector, relay 204, upon energizing over the fundamental circuit the second time, closes at armature 210 a circuit for driving sequence switch 200 out of position 6 and into position 7. This circuit includes the lower right-hand contact of cam 232 and said cam. When sequence switch 200 reaches position 7, the circuit for up-drive magnet 213 is again closed at cam 233 and its lower left-hand contact, whereupon the elevator starts to move up again and the brushes 252-254, inclusive, are tripped in the usual manner. When commutator brush 239 is brought into engagement with the first conducting segment of strip 244, ground is applied to the fundamental circuit by way of cam 234 and its upper right-hand contact, brush 239, strip 244, and the lower right-hand contact of cam 222 and said cam. When this occurs, relay 713 of the sender, Fig. 10, is short circuited and deenergizes as hereinbefore described. When brush 239 passes off the first conducting segment of strip 244, the shunt is removed from around relay 713 of the sender and said relay 713 energizes again.

As the elevator continues to move up, relay 713 of the sender is short circuited and deenergizes each time a conducting segment of strip 244 is reached, until the fourth conducting segment is reached, at which time counting relays 721-723, inclusive, of the sender have been energized in the previously described manner by the operation of relay 713 and conductor 743 is extended through to the junction of the windings of relay 730, and relay 730 is partly energized. Then, when relay 713 deenergizes in response to being short circuited the fourth time, relay 720 pulls all the way up and opens the fundamental circuit and closes a circuit for sequence switch 700 at armature 732.

In the incoming selector, the brushes 252-254, inclusive, are brought in engagement with the first trunk of the selected group at the same time that brush 239 passes off the fourth conducting segment of strip 244. Brush 239, upon passing off the fourth conducting segment of strip 244, opens the circuit of relay 204. Relay 204, upon deenergizing, opens the circuit of up-drive magnet 213 and closes the circuit of sequence switch 200 at armature 210, whereupon the elevator stops and sequence switch 200 moves from position 7 into position 8.

With sequence switch 200 in position 8, relay 204 energizes from ground by way of the upper left-hand contact of cam 231 and said cam, and the lower left-hand contact of cam 231. Upon energizing, relay 204 closes at armature 210 a circuit for sequence switch

200 by way of the lower right-hand contact of cam 232 and said cam, whereupon sequence switch 200 is advanced from position 8 to position 9.

- 5 In case the first trunk in the selected group is idle, relay 204 deenergizes in response to the opening of the circuit of its upper winding at the upper left-hand contact of cam 231 when sequence switch 200 advances beyond position $8\frac{1}{4}$, and no trunk hunting operation occurs.

Assuming the first trunk in the group to be busy, however, the following locking circuit for relay 204 is closed while sequence switch 200 is in position 8: from ground by way of the test contact of said trunk, test brush 254, upper left-hand contact of cam 221 and said cam, upper right-hand contact of cam 221, armature 211 and its working contact, upper right-hand contact of cam 223 and said cam, cam 222 and its upper right-hand contact, and the lower winding of relay 204 to battery. With relay 204 locked up over the above traced circuit, the 25 circuit of up-drive magnet 213 is again completed as follows when sequence switch 200 reaches position 9: from ground by way of the lower left-hand contact of cam 219 and said cam, armature 210 and its working contact, upper right-hand contact of cam 233 and said cam, lower left-hand contact of cam 233, and up-drive magnet 213 to battery. Consequently, the elevator is started upward again and carries the brushes 252-254, inclusive, over their terminals in search of an idle 30 trunk. While the brushes 252-254, inclusive, are passing from one set of terminals to the next, commutator brush 237 is in engagement with a conducting segment of strip 241 and 35 relay 204 is held energized over a circuit which is independent of test brush 254 and which extends as follows: from ground by way of the circuit as previously traced to cam 233 and thence by way of the lower 40 right-hand contact of cam 233, brush 237, strip 241, upper right-hand contact of cam 231 and said cam, lower left-hand contact of cam 231, and the upper winding of relay 204 to battery.

50 When an idle trunk is reached, which trunk it will be assumed is the one comprising conductors 255-257, inclusive, no ground is present on the test contact thereof, and, consequently, no circuit is completed for the lower 55 winding of relay 204. In this case, when the brushes have become accurately centered upon the terminals of the trunk, relay 204 deenergizes in response to brush 237 passing off the conducting segment of strip 241 and 60 opening the circuit of the upper winding of relay 204. Upon energizing, relay 204 opens a still further point in the circuit of its lower winding at armature 211, and at armature 210 opens the circuit of up-drive magnet 213, whereupon the upward movement of

the elevator stops, leaving the brushes 252-254, inclusive, in engagement with the terminals of the trunk comprising conductors 255-257, inclusive. As a further result of the deenergization of relay 204, a circuit is closed for sequence switch 200 at armature 210 by way of the lower left-hand contact of cam 232 and said cam. Sequence switch 200 now moves from position 9 into position 10, and is driven from position 10 to position 11 by its local contact, which does not open in position 10.

With sequence switch 200 in position 11, or to be more explicit, when sequence switch 200 has moved as far as position 10, test brush 254 is grounded by way of the lower left-hand contact of cam 221 and said cam, and the upper left-hand contact of cam 221. This makes the selected trunk test busy to the other selectors having access to it.

As a result of sequence switch 200 moving into position 11, relay 616 of the finder selector, Fig. 9, energizes over the following circuit: from ground by way of cam 314 of sequence switch 300, Fig. 5, and its upper left-hand contact, left-hand winding of relay 318, lower right-hand contact of cam 309 and said cam, upper left-hand contact of cam 309, trunk conductor 256, brush 253 of the incoming selector, upper right-hand contact of cam 228 of sequence switch 200 and said cam, lower left-hand contact of cam 228, conductor 248, brush 672 of the trunk finder, upper left-hand contact of cam 648 of sequence switch 600 and said cam, lower left-hand contact of cam 648, and the lower winding of relay 616 to battery. Relay 616 now energizes but does not produce any immediate effect. Relay 318 of the final selector, Fig. 5, does not energize over the above traced circuit for the reason that it is shunted by the resistance 328, which is shunted around the left-hand winding of relay 318 through cam 313 and its lower right-hand contact, the lower left-hand contact of cam 308 and said cam, and the upper right-hand contact of cam 308.

As a further result of sequence switch 200 of the incoming selector, Fig. 4, moving into position 11, the fundamental circuit is established for the final brush selection as follows: from ground by way of the previously traced circuit to conductor 249, Fig. 4, lower left-hand contact of cam 226 and said cam, lower right-hand contact of cam 226, brush 252, conductor 255, upper left-hand contact of cam 311 and said cam, cam 310 and its lower left-hand contact, and the right-hand winding of relay 319 to battery. In the sender, relay 713 energizes over the fundamental circuit and closes a circuit for the upper winding of counting relay 722 at armature 718 as follows: from ground by way of the working contact of armature 718 and said armature, cam 708 and its lower left-

hand contact (sequence switch 700 being in position 10), conductor 768, right-hand armature of relay 823 and its resting contact, right-hand armature of relay 822 and its 5 working contact (relay 822 having been energized during the hundreds registration as described hereinbefore), conductor 742, upper armature of relay 722 and its resting contact, and the upper winding of relay 722 10 to battery. Relay 722 now energizes part way with the hereinbefore described results.

Relay 319, of the final selector, upon energizing over the fundamental circuit, locks itself to the fundamental circuit independent 15 of the lower left-hand contact of cam 310 at armature 323. This locking circuit includes the lower right-hand contact of cam 310 and said cam. As a further result of the energization of relay 319, it closes a circuit for 20 relay 316 at armature 322 by way of cam 302 and its lower left-hand contact. Relay 316, upon energizing, locks itself to the grounded conductor 257 at armature 320, and at armature 321 closes a circuit for sequence 25 switch 300 by way of the lower left-hand contact of cam 304 and said cam. Sequence switch 300 now advances from position 1 to 30 position 2, whereupon the initial circuits of relays 316 and 319 are opened at cam 304 and its lower left-hand contact and cam 310 and its lower left-hand contact, respectively, leaving said relays energized over their respective locking circuits mentioned above.

As a result of sequence switch 300 moving 35 into position 2, a circuit for the high speed up-drive magnet 334 is completed at cam 305 as follows: from ground by way of armature 322 and its working contact, cam 305 and its lower left-hand contact, and magnet 334 to 40 battery. Accordingly, the elevator is started upward to make the brush selection. Each time commutator brush 339 comes into engagement with a conducting segment of commutator strip 342, the sending relay of the 45 sender is short circuited and deenergizes in response to ground being applied to the fundamental circuit as follows: from ground by way of armature 322 and its working contact, cam 302 and its lower right-hand contact, brush 339, commutator strip 342, and the lower right-hand contact of cam 311 and 50 said cam.

In the sender, Fig. 10, each time relay 713 deenergizes in response to being short circuited in the above described manner, it removes ground from cams 705 and 708 at armature 718. In response to the first deenergization of relay 713, counting relay 722 pulls all the way up, and in response to the 60 third deenergization of relay 713, counting relay 720 pulls all the way up and opens the fundamental circuit at armature 732, and moves sequence switch 700 from position 10 to position 12.

65 When this occurs, the commutator brush

339 of the final selector, Fig. 5, is in engagement with the third conducting segment of commutator strip 342, and when brush 339 comes into engagement with the next insulated segment of strip 342, the circuit of relay 70 319 is opened. Relay 319, upon deenergizing, opens the circuit of the high speed up-drive magnet 334 at armature 322, and closes a circuit for sequence switch 300 by way of armature 322 and its resting contact and the 75 upper right-hand contact of cam 307. Consequently, the elevator stops moving upward and sequence switch 300 moves from position 2 to position 3; closes the fundamental circuit again at cam 310 and its lower left-hand contact; and at cam 303 closes a circuit for trip magnet 331, whereupon the trip magnet energizes preparatory to tripping the No. 2 set of brushes when the elevator starts upward again. Relay 713 now energizes again over the fundamental circuit in series with relay 319 of the final selector, and closes a circuit for the upper winding of 80 counting relay 723 as follows: from ground by way of the working contact of armature 718 and said armature, cam 708 and its lower right-hand contact, conductor 769, right-hand armature of relay 834 and its resting contact, right-hand armature of relay 833 and its working contact relays 831-833, inclusive, having been energized in response to the transfer of the tens registration as explained hereinbefore, second armature of 85 relay 832, counting from the right, and its 90 plained hereinbefore, second armature of relay 831 and its working contact, conductor 743, and the upper armature of relay 723 and its working contact to battery by way of the upper winding of relay 723. Relay 723 pulls half way up over this circuit and closes the 95 usual locking circuit for itself at its lower armature.

In the final selector, relay 319, upon energizing over the fundamental circuit, closes the usual locking circuit for itself at armature 323 and at armature 322 closes a circuit for sequence switch 300 by way of the upper left-hand contact of cam 307 and said cam. Sequence switch 300 now moves out of position 3 and into positon 4, thereby opening 110 the initial circuit of relay 319 at the lower left-hand contact of cam 310, leaving relay 319 locked up through the lower right-hand contact of cam 310 and armature 323 and its working contact. As a further result of sequence switch 300 moving into position 4, the circuit of the high speed up-drive magnet 334 is again closed through armature 322 and its working contact and cam 305 and its lower left-hand contact. Consequently, the 115 elevator starts up to select the desired tens group of lines, whereupon the selected set of brushes is tripped.

As the elevator travels upward, commutator brush 338 is brought into engagement suc- 120 125 130

- cessively with the conducting segments of commutator strip 341, and places direct ground upon the fundamental circuit upon coming into engagement with each of said 5 conducting segments, whereupon relay 713 of the sender responds by deenergizing in the usual manner. When the brush 338 comes into engagement with the No. 3 conducting segment of strip 341, relay 713 of the sender, 10 Fig. 10, deenergizes the fourth time, whereupon relay 720 energizes fully and opens the fundamental circuit at armature 732, at the same time starting the sequence switch on its way from position 12 to position 14, with 15 results similar to those hereinbefore described.
- Relay 319, Fig. 5, deenergizes as soon as brush 338 passes off the No. 3 conducting segment of strip 341; opens the circuit of up-drive magnet 334 at armature 322; and at armature 322 closes a circuit for sequence switch 300 by way of the upper right-hand contact of cam 307 and said cam. Sequence 20 switch 300 now advances from position 4 to position 5, whereupon the fundamental circuit is again established at the lower left-hand contact of cam 310, and relay 319 energizes in series with relay 713 of the sender, Fig. 10.
- Since sequence switch 700 of the sender is in position 14 and, since said register relays 842 and 844 are energized in accordance with the unit's digit 7, the energization of relay 713 over the fundamental circuit closes a 25 circuit for the seventh counting relay 727 as follows: from ground by way of the working contact of armature 718 and said armature, cam 708 and its upper right-hand contact, conductor 770, right-hand armature of relay 844 and its working contact, middle armature of relay 843 and its resting contact, third armature, counting from the right, of relay 842 and its working contact, conductor 747, upper armature of relay 727 and its resting contact, and the upper winding of relay 727 to battery. Relay 727 now pulls part way up in the usual manner and closes a locking circuit for itself at its lower armature. 30 In the final selector, Fig. 5, relay 319, upon energizing over the fundamental circuit in response to the sequence switch 300 moving into position 5 as pointed out above, establishes the usual locking circuit for itself at armature 323, and at armature 322 closes a circuit for sequence switch 300 by way of the upper left-hand contact of cam 307 and said cam. Sequence switch 300 now moves out of position 5 and into position 6, whereupon a circuit is completed for the low speed up-drive magnet 333 as follows: from ground by way of armature 322 and its working contact, cam 302 and its upper left-hand contact, and magnet 333 to battery. Upon energizing, 35 magnet 333 presses the tape against roller 329, and starts the elevator moving upward at a low speed so as to enable the brushes to stop on the desired line. During the units selection, the fundamental circuit is grounded each time commutator brush 339 comes 40 into engagement with a conducting segment of strip 342, strip 342 being connected with the fundamental circuit by way of the lower right-hand contact of cam 311 and said cam. This causes relay 713, Fig. 10, of the sender 45 to deenergize each time brush 339 of the final selector comes into engagement with a conducting segment of strip 342. When brush 339 comes into engagement with the No. 7 50 conducting segment of strip 342, or when the brushes 343-345, inclusive, are just beneath the seventh set of terminals in the selected group, relay 713 of the sender deenergizes the eighth time, whereupon relay 720 pulls all the way up with the hereinbefore 55 described results, which are to open the fundamental circuit and to advance the sequence switch.
- In the final selector, brushes 343-345, inclusive, become centered on the terminals of conductors 346-348, inclusive, respectively, of the desired line at the same time that the commutator brush 339 passes off the No. 7 60 conducting segment of strip 342 and opens the circuit of relay 319. Upon deenergizing, 65 relay 319 opens the circuit of up-drive magnet 333 at armature 332 and closes a circuit for sequence switch 300 by way of the upper right-hand contact of cam 307 and said cam. Sequence switch 300 now moves from position 6 to position 7, and closes a point in the fundamental circuit again at cam 310 and its lower left-hand contact. Relay 319, however, does not energize immediately for the reason that the fundamental circuit is open 70 at another point.
- In the sender, Fig. 10, sequence switch 700, upon being driven out of position 14 in response to the energization of relay 720, as described above, moves into position 15 and 75 is then driven to position 18 by its local contact which does not open in positions 15-17, inclusive. As a result of sequence switch 700 moving out of position 14, ground is removed in the usual manner from the locking conductor by cam 701, whereupon counting relays 720-727, inclusive, deenergize. When sequence switch 700 arrives in position 15, a circuit is closed for sequence switch 600 of the 80 finder-selector link, Fig. 9, as follows: from ground by way of the lower right-hand contact of cam 706, Fig. 10, and said cam, conductor 751, brush 606, lower right-hand contact of cam 650 and said cam, and sequence switch 600 to battery. Sequence switch 600 85 now moves from position 8 to position 9, whereupon the busy potential is removed from brush 607 at cam 645. When this occurs, relay 712 of the sender deenergizes owing to the fact that it is differentially 90

wound, and at armature 717 closes a circuit for sequence switch 700, whereupon sequence switch 700 advances from position 18 to position 1. The sender is now at normal and is ready to handle another call.

In the finder selector, Fig. 9, as a further result of sequence switch 600 moving from position 8 to position 9, sequence switch 600 is driven from position 9 to position 10 over the following circuit: from ground by way of armature 625 and its working contact, upper right-hand contact of cam 647 and said cam, and the magnet of sequence switch 600 to battery. With sequence switch 600 in either position 9 or position 10, ground by way of armature 627 and its resting contact is placed on the fundamental circuit at the lower left-hand contact of cam 638 and said cam, and the upper right-hand contact of cam 638.

In the final selector, relay 319 now energizes over the fundamental circuit in response to the above mentioned grounding of said circuit; closes a locking circuit for itself through cam 310 and its lower right-hand contact at armature 323; and closes at armature 322 a circuit for sequence switch 300 by way of the upper left-hand contact of cam 307 and said cam. Sequence switch 300 now moves from position 7 to position 8, and is advanced from position 8 to position 9 by its local contact which does not open in position 8.

It will be noted that the locking circuit of relay 319 is opened at cam 310 and its lower right-hand contact in response to sequence switch 300 moving out of position $7\frac{1}{2}$. Relay 319, however, does not deenergize at this time owing to a locking circuit which is closed through cam 313 and its lower left-hand contact and armature 323 and its working contact, upon sequence switch 300 reaching position $7\frac{3}{4}$. It may be explained that it is the usual practice to cut the sequence switch cams so that they make contact one-quarter of a position either way from the position indicated. For example, when position $7\frac{1}{2}$ is indicated, the contact does not open until position $7\frac{3}{4}$ is reached, and when position $7\frac{3}{4}$ is indicated, the contact closes as early as position $7\frac{1}{2}$. This overlapping arrangement takes care of the transfer of relay circuits from one cam to another while the sequence switch is in motion.

As a result of sequence switch 300 moving out of position 8 as above described, the circuit of relay 616 of the finder selector link, Fig. 9, which circuit includes conductor 256, is opened at cam 309. Relay 616, upon de-energizing, closes a circuit for sequence switch 600 at armature 625 by way of the upper left-hand contact of cam 647 and said cam, whereupon sequence switch 600 advances from position 10 to position 11.

With sequence switch 600 in position 11, a

circuit is closed for sequence switch 200 of the incoming selector, Fig. 4, as follows: from ground by way of cam 641 of sequence switch 600, Fig. 9, and its upper left-hand contact, working contact of armature 619 and said armature, brush 669, conductor 251, lower right-hand contact of cam 229 and said cam (sequence switch 200 being in position 11), and sequence switch 200 to battery. Sequence switch 200 now advances from position 11 to position 12 and closes at cam 223 a circuit for the lower winding of relay 204 as follows: from ground by way of the lower left-hand contact of cam 223 and said cam, cam 222 and its upper right-hand contact, and the lower winding of relay 204 to battery. Relay 204, upon energizing, closes a circuit for sequence switch 200 at armature 210 as follows: from ground by way of the lower left-hand contact of cam 219 and said cam, armature 210 and its working contact, lower right-hand contact of cam 232 and said cam, and the magnet of sequence switch 200 to battery. Sequence switch 200 is advanced from 12 to 13 in response to the closure of this circuit and is driven from position 13 to position 14 by its local contact which does not open in position 13.

A circuit is closed for relay 203 when sequence switch 200 reaches position 13, and remains closed while sequence switch 200 is in position 14. This circuit is as follows: from ground by way of the lower left-hand contact of cam 223 and said cam, upper left-hand contact of cam 223, relay 203, armature 207 and its resting contact, and armature 205 and its resting contact to battery. Relay 203, upon energizing, separates the talking conductors of the selector extending to the brushes from conductors 125 and 129 at armatures 208 and 209; grounds the section of talking conductor which extends to brush 252 at the normally closed contacts controlled by armature 208; and at armature 209 connects the section of talking conductor that extends to brush 253 to the ringing lead 217 by way of ringing trip relay 201 which is connected to ringing lead 217 by cam 218 when sequence switch 200 reaches position 14. Ringing current from the ringing machine RM is now projected out to the final selector through brush 253, and a return path to ground is afforded over brush 252 which becomes effective only after the circuit has been completed by the final selector as will be explained subsequently. The small condenser 245 allows enough ringing current to leak back over conductor 125 to give the calling subscriber an audible ringing signal.

As a further result of sequence switch 200 moving out of position 11 as described in the preceding paragraph, the circuit of holding relay 615, Fig. 9, is opened at the upper left-hand contact of cam 224. Relay 615,

upon deenergizing, open the circuit of relay 614 at armature 622. Upon deenergizing, relay 614 closes a circuit for sequence switch 600 at armature 629 by way of the upper left-hand contact of cam 650 and said cam. Sequence switch 600 now moves from position 11 into position 12.

With sequence switch 600 in position 12, down-drive magnet 660 of the trunk finder 10 is operated through cam 641 and its lower right-hand contact, and down-drive magnet 602 of the sender selector is operated through armature 625 and its resting contact, upper left-hand contact of cam 643 and said cam, 15 and the lower right-hand contact of cam 643. Consequently, the sender selector and the trunk finder now return to normal.

Assuming that the sender selector reaches normal first, relay 616 is energized over the 20 following circuit in response to commutator brush 609 coming into engagement with contact 611: from ground by way of cam 640 and its upper right-hand contact, commutator brush 609, commutator 611, lower right-hand 25 contact of cam 638 and said cam, upper left-hand contact of cam 638, and the upper winding of relay 616 to battery. Upon energizing, relay 616 opens the circuit of down-drive magnet 602 and prepares a circuit for moving sequence switch 600 out of position 13 at armature 625.

Assuming now that the trunk finder reaches normal, sequence switch 600 is advanced out of position 12 upon its circuit being closed 30 at commutator brush 664 through commutator 666 and through the lower left-hand contact of cam 647 and said cam. The circuit of down-drive magnet 660 is opened at cam 641 and its lower right-hand contact when 35 sequence switch 600 moves out of position 12. Since, according to the above assumption, relay 616 is energized at this time, sequence switch 600 does not stop in position 13, but is driven out of position 13 on account of 40 its circuit being closed through armature 625 and its working contact and the upper right-hand contact of cam 647 and said cam.

Sequence switch 600 is now advanced through positions 14-16, inclusive, by its 50 local contact which does not open in these positions and waits in position 17 to be assigned again. As a result of sequence switch 600 moving out of position 16, ground is removed from conductor 864 at the lower left-hand contact of cam 640. This allows the finder-selector allotter, Fig. 12, to stop on the finder selector so as to allot it for another call.

Returning now to the final selector, Fig. 5, 60 its operation will be taken up where it was last left off. As a further result of sequence switch 300 of the final selector, Fig. 5, moving into position 9 as described above, relay 318 is energized over the following circuit: from 65 ground by way of armature 322 and its work-

ing contact, cam 305 and its upper right-hand contact, left-hand winding of relay 318, upper right-hand contact of cam 308 and said cam, and the upper left-hand contact of cam 308 to battery. Upon energizing, relay 318 connects up test brush 345 to the winding of relay 317 at armature 326, the upper right-hand contact of cam 315 being closed in position 9.

Assuming the called line to be busy, there 70 is a battery potential on private normal conductor 348 and test relay 317 of the final selector energizes over the following circuit: from ground by way of cam 301 and its lower left-hand contact, test relay 317, working 75 contact of armature 326 and said armature, cam 315 and its upper right-hand contact, and test brush 345 to battery. Upon energizing, relay 317 closes a circuit for the right-hand winding of the already energized relay 80 318 at armature 369. As a further result of the above energization of relay 318, it closes at armature 325 a circuit for moving sequence 85 switch 300 from position 9 to position 10. This circuit is as follows: from ground by 90 way of cam 314 and its lower left-hand contact, armature 325 and its working contact, lower left-hand contact of cam 307 and said cam, and sequence switch 300 to battery. Sequence switch 300, upon being advanced from 95 position 9 to position 10, opens the circuit of relay 319 at cam 303, whereupon relay 319 deenergizes, but does not produce any immediate effect.

The local contact of sequence switch 300 100 does not open in position 10 and sequence switch 300 moves into position 11. Sequence switch 300 is moved out of position 11 by the closure of a circuit which includes armature 322 and its resting contact and the upper 105 right-hand contact of cam 307 and said cam.

When sequence switch 300 arrives in position 12, relay 319 energizes over the following circuit: from ground by way of cam 314 and its lower left-hand contact, armature 325 and its working contact, lower left-hand contact of cam 311 and said cam, cam 310 and its lower left-hand contact, and the right-hand winding of relay 319 to battery. Upon energizing, relay 319 closes a locking circuit 110 for itself at armature 323 from ground by way of cam 303 and its lower left-hand contact. As a further result of the energization of relay 319, it closes a circuit for sequence switch 300 at armature 322 by way of the upper left-hand contact of cam 307 and said cam. Sequence switch 300 now moves from 115 position 12 to position 13 and is advanced from position 13 to position 14 by its local contact which does not open in position 13.

As a result of sequence switch 300 moving out of position 13, test relay 317 is disconnected at cam 301 and its lower left-hand contact. Upon deenergizing, relay 317 opens the circuit of relay 318 at armature 329, 120 125 130

whereupon relay 318 deenergizes but does not produce any immediate effect.

When sequence switch 300 arrives in position 14, the circuit of down-drive magnet 322 is closed at cam 305 and its lower right-hand contact and includes armature 322 and its working contact. In response to the energization of down-drive magnet 322, the elevator is returned to normal, whereupon brush 338 comes into engagement with normal contact 370 and closes a circuit for sequence switch 300 as follows: from ground by way of cam 301 and its upper left-hand contact, brush 338, normal contact 370, upper right-hand contact of cam 304 and said cam, and the magnet of sequence switch 300 to battery. Sequence switch 300 now advances out of position 14 and opens the circuit of down-drive magnet 322 at cam 305 and its lower right-hand contact. The circuit of sequence switch 300 remains closed and the sequence switch continues to advance until it advances out of position 16 on its way to position 17, at which time its circuit is opened at the upper right-hand contact of cam 304 and said cam. Sequence switch 300 is carried the remaining distance to position 17 by its local contact in the usual manner. Upon reaching position 17, sequence switch 300 connects up the busy 30 flash interrupter 311 to one terminal of the left-hand winding of relay 318 at cam 313 and its upper right-hand contact. The other terminal of the left-hand winding of relay 318 is connected to battery at this time 35 by way of the upper right-hand contact of cam 308 and said cam, and the upper left-hand contact of cam 308. Consequently, relay 318 begins to energize and deenergize under the control of interrupter 311. Each 40 time relay 318 energizes, it connects the left-hand winding of the busy tone transformer to the lower heavy talking conductor at armature 326 by way of the lower right-hand contact of cam 312 and said cam, armature 326 45 being connected to the left-hand winding of the busy tone transformer by way of cam 315 and its lower left-hand contact and resistance 327. The first time relay 318 energizes, a circuit is closed for ringing trip relay 201 of 50 the incoming selector as follows: from battery by way of the left-hand winding of the busy tone transformer, Fig. 5, previously traced circuit to the lower heavy talking conductor 256, brush 253 of the incoming selector, upper right-hand contact of cam 228 of sequence switch 200 and said cam, upper left-hand contact of cam 228, armature 209 and its working contact, ringing trip relay 201, cam 218 and its associated contact, and thence 55 to high voltage battery by way of either the resting or working contact of the armature of the ringing relay. Relay 201 energizes over this circuit on account of the fact that current flows through its winding from the 60 high voltage battery, and returns through

the common ground lead by way of the regular exchange battery. Upon energizing, relay 201 removes a shunt from around the lower winding of relay 202 at armature 205, whereupon relay 202 energizes in series with 70 relay 203. Upon energizing, relay 202 closes a locking circuit for its upper winding at armature 206 by way of cam 220 and its associated contact, and at armature 207 places a shunt around relay 203, whereupon relay 203 75 deenergizes and connects up the heavy talking conductors 125 and 130 to the brushes 252 and 253. Relay 201 now deenergizes but does not produce any particular result at this time.

The talking conductors are now connected 80 through from the trunk circuit TC, Fig. 2, to the final selector, and each time relay 318 of the final selector energizes after the ringing circuit of the incoming selector is tripped, as above described, the tone produced by the 85 busy machine is sent back over the circuit previously traced to armature 209 of relay 203, Fig. 4, and thence by way of the lower heavy talking conductor 130, and the lower right-hand winding of the repeating coil of 90 the trunk circuit TC to battery. The busy tone, which is produced by the busy machine associated with the final selector and sent back over this circuit, is repeated through the left-hand repeating coil windings, thereby 95 giving the calling subscriber the usual intermittent busy signal. However, supervisory relay 107, which is bridged around the low resistance 108, is not operated at this time owing to the fact that no flow of battery current takes place over conductor 130 because said conductor is connected to the same pole of the same battery at both ends. The calling subscriber, upon hearing the busy 100 tone, knows that the desired line is for the 105 time being inaccessible and he replaces his receiver, whereupon the connection is released in the usual manner.

Referring now to the final selector, Fig. 5, it will be noted that as a further result of each 110 of the energizations of relay 318 under the control of interrupter 311, battery through the high resistance 375 is placed on the upper talking conductor 255 by way of the following circuit: from battery by way of the 115 upper left-hand contact of cam 308 and said cam, lower right-hand contact of cam 308, resistance 375, armature 325 and its working contact, lower left-hand contact of cam 311 and said cam, and the upper left-hand contact of cam 311. These light impulses of battery do not have any particular function in this case, but are used in other cases, such as for example, to give flashing supervision 120 to a calling operator when the final selector is seized by way of another path. Incidentally, in this case, these impulses are transmitted back over the upper heavy talking conductor through the incoming selector, Fig. 4, to ground by way of the upper right-hand 125 130

winding of the repeating coil associated with the trunk circuit TC, Fig. 2.

Assuming now that the desired line is idle when called, there is no potential upon 5 private normal conductor 348 associated with the called line, and test relay 317 of the final selector does not energize in response to being connected up by relay 318 when the latter relay energizes. The above mentioned energization of relay 318 occurs while sequence switch 300 is in position 9. Sequence switch 300 is driven from position 9 to position 12 in the hereinbefore described manner, and 10 relay 318 deenergizes when the circuit of its left-hand winding is opened at cam 308 in response to sequence switch 300 moving out of position 9 as above described. Upon deenergizing, relay 318 opens a point in the 15 circuit of relay 319, and prepares a circuit for sequence switch 300 at armature 325 so as to prevent the energization of relay 319, and to advance the sequence switch when the latter arrives in position 12.

As a further result of the deenergization 20 of relay 318, it places battery on private normal conductor 348 at armature 326 by way of the following circuit: from battery by way of the upper left-hand contact of cam 308 and said cam, lower left-hand contact of cam 308, resistance 328, resting contact of armature 326 and said armature, cam 315 and its upper right-hand contact, and brush 345. This battery potential causes the called line to test busy to the other final selectors 25 having access to it and operates cut-off relay 349, which relay clears the called line of its attachments in the usual manner. Sequence switch 300, upon reaching position 12 in this case, is advanced from position 12 to position 30 13 over the following circuit: from ground by way of cam 314 and its lower left-hand contact, armature 325 and its resting contact (relay 318 being deenergized in this case), and the lower right-hand contact of cam 307 and said cam to battery by way 35 of the magnet of sequence switch 300.

Sequence switch 300 is advanced out of position 13 and into position 14 by its local contact in the usual manner, but since relay 319 is deenergized at this time on account of relay 318 having been deenergized when sequence switch 300 reached position 12, the circuit of down-drive magnet 332 is not closed 40 in this position as is the case when the called line is busy, and sequence switch 300 is advanced out of position 14 by a circuit which includes armature 322 of relay 319 and its resting contact, and the upper right-hand contact of cam 307 and said cam. When sequence switch 300 arrives in position 15, the conductors 255 and 256 are connected through to the brushes 243 and 244 at cams 311 and 312.

65 The called subscriber's bell is now rung

intermittently in the usual manner by ringing current which is placed on the lower trunk conductor 256 by way of brush 253 of the incoming selector, the ringing current being controlled by the ringing machine RM, 70 Fig. 4, over the common ringing conductor 317. The return circuit for the ringing current is over the upper talking conductor 255 to ground in the incoming selector.

When the subscriber at substation A' responds to the ringing of his bell by removing his receiver, a direct current circuit is closed over his line conductors, whereupon ringing trip relay 201, Fig. 4, energizes, with the result that the two sections of the trunk are 75 united in the hereinbefore described manner, thereby finally completing the talking circuit.

Supervisory relay 107 in the trunk circuit TC, Fig. 2, now energizes over the called subscriber's loop in multiple with resistance 108 80 and closes at armature 124 a circuit for reversing relay 109. Reversing relay 109, upon energizing, reverses trunk conductors 72 and 73 as regards their connection with line relay 102, thereby causing a reversal in the direction of current flow in conductors 72 and 73. When this occurs, electro-polarized relay 61 in the repeater F, Fig. 1, energizes 85 and reverses the current flow in the calling line at armatures 65 and 66. This reversal does not perform any particular function in this case, but, as is well-known, is used in certain cases to give supervision to calling operators and for operating meters and coin boxes and the like.

100 The calling and called subscribers may now converse with each other as desired, over the talking circuit which is outlined by the heavy talking conductors, talking battery being supplied to the calling substation A 105 through line relay 62 and through the left-hand winding of the repeating coil of the repeater F, and talking battery being supplied to the called substation A' through the right-hand repeating coil windings of the repeating coil associated with the trunk circuit TC.

Upon the termination of the ensuing conversation, the two subscribers replace their receivers. When the receiver is replaced at substation A', the supervisory relay 107 in the trunk circuit TC, Fig. 2, deenergizes and opens the circuit of reversing relay 101, whereupon the current flow in conductors 72 and 73 is reversed to normal. In response to this reversal, electro-polarized relay 61 in the repeater F, Fig. 1, deenergizes and reverses the current flow in the calling line to normal.

115 When the receiver is replaced at substation A, the circuit of line relay 62 of repeater F is opened. Upon deenergizing, relay 62 opens the bridge across trunk conductors 72 and 73 at armature 68, and at armature 67 opens the circuit of release relay 63. Incidentally, relay 64 is energized at this time 120 125 130

in the usual manner. Release relay 63 de-energizes in response to the prolonged opening of its circuit; opens the circuit of relay 64 at armature 70; and at armature 69 re-
 5 moves ground from release trunk conductor 50, thereby opening the circuit of the upper winding of electro-polarized relay 61. As a further result of the removal of the ground potential from release trunk conductor 50,
 10 switching relay 5 of the line switch C, switching relay 29 of the selector D, and the corresponding relay (not shown) of the selector E deenergize. The deenergization of switching relay 5 of the line switch C re-
 15 stores conditions in the line switch C to normal, and the deenergization of the switching relays of the selectors D and E results in the closure of the circuits of the respective associated release magnets, the circuit of release
 20 magnet 30 of the selector D being closed at armature 44 of switching relay 29. This circuit includes armature 36 and its resting contact, armature 38 and its resting contact, and off normal contacts 31. Upon the energiza-
 25 tion of release magnet 30, the wipers of the selector D are restored to normal in the usual manner and the circuit of release magnet 30 is opened at off normal contacts 31 by the switch shaft when the latter reaches its nor-
 30 mal position. The selector E, of course, is restored to normal in a similar manner.

In the panel office, line relay 102 of the trunk circuit TC deenergizes in response to the opening of its circuit by the line relay
 35 of the repeater F as above described. Upon deenergizing, relay 102 opens the circuit of release relay 103, and release relay 103, upon deenergizing, disconnects switching relay 141 of the secondary switch SS at armature
 40 115; disconnects armature 143 of relay 141 at armature 114, and at armature 113 opens the locking circuit of relays 104 and 106, whereupon relays 104 and 106 deenergize. The deenergization of relay 104 does not pro-
 45 duce any particular result at this time, but relay 106, upon deenergizing, places ground on release conductor 127 extending to the incoming selector, Fig. 4. When this occurs, sequence switch 200 is operated over a cir-
 50 55 cuit which extends from ground by way of release conductor 127, upper left-hand contact of cam 229 and said cam, and the magnet of sequence switch 200 to battery. Sequence switch 200 is advanced to and through posi-
 60 65 tion 17 over this circuit and when position 18 is reached, a circuit for down-drive magnet 214 is closed at cam 234 and its lower left-hand contact. When this occurs, the elevator is returned to normal in the usual manner and when brush 237 comes into engagement with commutator segment 240, a circuit is closed for sequence switch 200 as follows: from ground by way of cam 234 and its upper right-hand contact, brush 237, seg-
 65 70 ment 240, upper right-hand contact of cam

229 and said cam, and the magnet of sequence switch 200 to battery. Sequence switch 200 now advances from position 18 to position 1, its initial circuit being opened at cam 229 when it leaves position 18. 70

Regarding the release of the final selector, it may be said that in response to sequence switch 200 moving beyond position $16\frac{1}{4}$ as above described, ground is removed from test brush 254 at the lower left-hand contact of cam 221. When this occurs, relay 316 of the final selector deenergizes and opens its lock-
 75 80 ing circuit at armature 320, and at armature 320 and its resting contact replaces the ground potential on conductor 257 through cam 303 and its upper right-hand contact so as to guard the switch against seizure until the sequence switch has advanced as far as position 18. As a further result of the de-
 85 90 energization of relay 316, it closes a circuit for relay 319 at armature 321 by way of the lower left-hand contact of cam 309 and said cam, the upper right-hand contact of cam 309, and the left-hand winding of relay 319. Relay 319, upon energizing, closes a circuit for sequence switch 300 at armature 322. This circuit includes the upper left-hand contact of cam 307 and said cam. Sequence switch 300 now moves from position 15 to position 16, whereupon the circuit of relay 95

the same time at the lower right-hand contacts of cams 302 and 305. The final selector is rendered accessible again in response to the removal of ground from conductor 257 at cam 303 and its upper right-hand contact when sequence switch 300 moves out of position 18.

Regarding the freeing of the called line, the circuit of cut-off relay 349 of the called line is opened at cam 315 and its upper right-hand contact as soon as sequence switch 300 has advanced beyond position 16½.

The entire connection is now released and the common apparatus is restored to common use.

Referring now particularly to the register set shown in Fig. 6, the function of the common interrupter 372 together with certain associated equipment will be explained a little more in detail. It happens occasionally that a subscriber dials part of a number and neither finishes dialling nor replaces his receiver for a considerable length of time. In case no special provisions were made, an incident of this nature would result in the tying up of the register set shown in Fig. 6 until the calling subscriber either replaced his receiver or finished dialling the number. When the calling subscriber waits too long, however, in dialling a number, an alarm is given to an attendant in a manner which will be pointed out now. It will be remembered that release relay 362 of the register R is energized when the register set is seized and connects up the common interrupter 372 at armature 373. This interrupter moves very slowly and is set so as to allow plenty of time for the four digits in the subscriber's number to be dialled, and the number registration transferred as hereinbefore described, before it makes one complete revolution.

The first time interrupter 372 grounds the associated common conductor after the register set shown is seized, a circuit is closed for the upper winding of relay 477 of the register R' by way of the working contact of armature 373 and armature 492 and its resting contact. Relay 477 is a marginal two-step relay of practically the same design and adjustment as any one of the ten counting relays 720-729, inclusive, of the sender, Fig. 10, already described. Accordingly, relay 477 energizes through its upper winding just far enough to cause armature 492 to come into engagement with its working contact.

When ground is removed from the associated common conductor by interrupter 372, the shunt is removed from around the lower winding of relay 477, whereupon relay 477 energizes fully; prepares a locking circuit for the common signal relay 495 at armature 493; and at armature 492 disconnects its own upper winding from the interrupter circuit and extends the interrupter circuit to the upper winding of relay 495. Relay 495, it

may be explained, is common to all the register sets.

With the above mentioned condition existing, if the calling subscriber does not complete the dialling of his number, and thereby bring about the release of his register set in the previously described manner before the interrupter 372 grounds the associated common conductor the next time, a circuit is completed for the upper winding of relay 495 upon the next operation of said interrupter by way of armature 492 and its working contact. Relay 495, upon energizing, closes a locking circuit for its lower winding at armature 496 through armature 493 and its working contact. As a further result of the energization of relay 495, it places ground on the alarm conductor 498 at armature 477, whereupon the necessary alarm is given to an attendant in any well-known or desired manner. The attendant may respond to the alarm and take such steps as he sees fit to clear up the trouble.

Assuming now that the trunk circuit TC, Fig. 2, is seized in the usual manner, and that all the register sets accessible to the secondary switch SS are busy, the secondary switch SS is unable to find an idle trunk and, consequently, switching relay 141 is deenergized, and the wipers of the switch are still hunting when the calling subscriber next turns his calling device. In this case, the impulses of current which are otherwise transmitted through wiper 147 of the secondary switch to the magnet operating circuit of the seized register set are transmitted to the upper winding of relay 105 over the following circuit: from ground by way of armature 112 and its resting contact, working contact of armature 114 and said armature, armature 143 of switching relay 141 of the secondary switch SS and its resting contact (switching relay 141 being deenergized at this time according to the above assumption), resting contact of armature 116 and said armature, and the upper winding of relay 105 to battery. Relay 105, upon energizing in response to the first of these impulses of current, disconnects test wiper 149 of the secondary switch from the junction of switching relay 141 and stepping magnet 142 at armature 121 so as to stop the selecting movement of the switch; disconnects switching relay 141 at armature 120 so as to prevent it from energizing; and at armature 120 and its working contact completes a locking circuit for the lower winding of relay 105, which includes the working contact of armature 113 and said armature, and armature 117 and its resting contact. As a further result of the energization of relay 105, it connects a lead from the right-hand winding of the associated busy tone transformer to the upper talking conductor at armature 119. In response to this operation, the calling sub-

scriber is given the usual busy tone which informs him that he cannot obtain the desired connection for the time being and, when he replaces his receiver, the partly established connection is released in the usual manner.

- 6 Referring now particularly to Fig. 4, the operation of the incoming selector and associated equipment when all the trunks in the selected group are busy will be explained.
- 10 Assuming that the trunk associated with the incoming selector has been seized and that the call has proceeded as hereinbefore described, until the brushes 252-254, inclusive, have been tripped, and until the group selecting operation has been completed and the trunk hunting movement initiated, and assuming that all the trunks in the selected group are busy, relay 204 deenergizes in the usual manner just as though an idle trunk were reached
- 15 when the brushes 252-254, inclusive, pass off the terminals of the last trunk in the group. At the same time, brush 238 comes into engagement with a conducting segment on the upper part of commutator strip 243, which
- 20 is the case only when the elevator has been moved up far enough to carry the brushes above the upper set of terminals in the group.

In response to the above named deenergization of relay 204, the circuit of up-drive magnet 213 is opened at armature 210, and a circuit is closed for sequence switch 200 by way of the lower left-hand contact of cam 232 and said cam. When this occurs, sequence switch 200 moves from position 9 to

35 position 10, and is carried from position 10 to position 11 by its local contact which does not open in position 10.

Sequence switch 200 is moved out of position 11 upon being energized over a circuit

40 which includes commutator brush 238 and an overflow conducting segment on commutator strip 243 and is as follows: from ground by way of cam 234 and its upper right-hand contact, brush 238, strip 243, lower left-hand

45 contact of cam 229 and said cam, and sequence switch 200 to battery.

When sequence switch 200 reaches position 12, relay 204 energizes over the following circuit: from ground by way of the lower left-hand contact of cam 223 and said cam, cam 222 and its upper right-hand contact, and the lower winding of relay 204 to battery. Relay 204, upon energizing, closes a circuit for sequence switch 200 at armature

55 210 by way of the lower right-hand contact of cam 232 and said cam. Sequence switch 200 is advanced from position 12 to position 13 over this circuit, but is not advanced beyond position 13 by this circuit for the reason that ground is removed from cam 219 at the lower left-hand contact thereof in response to sequence switch 200 moving beyond position 12 $\frac{1}{4}$.

Since, brush 238 is in engagement with a

50 conducting segment of the overflow commu-

tater 243 at this time, sequence switch 200 is moved from position 13 to position 17, over the following circuit: from ground by way of cam 234 and its upper right-hand contact, brush 238, strip 243, lower left-hand contact of cam 229 and said cam, and sequence switch 200 to battery.

When sequence switch 200 reaches position 17, ground is placed on conductor 128 at cam 233 by way of the following circuit: from ground by way of the upper left-hand contact of cam 233 and said cam, upper right-hand contact of cam 233, working contact of armature 210 and said armature, and cam 219 and its upper left-hand contact to conductor 128.

In the trunk circuit TC, Fig. 2, relay 105 energizes through armature 116 and its working contact and its own upper winding in response to ground being placed on conductor 128. Upon energizing, relay 105 connects a lead from the left-hand winding of the associated busy tone transformer to the upper talking conductor at armature 119, whereupon the calling subscriber is given the busy tone as hereinbefore described.

In this case, when the calling subscriber replaces his receiver, the apparatus in the step by step office is released in the hereinbefore described manner, and release relay 103 of the trunk circuit TC in the panel office, upon deenergizing in response to the hanging up of the calling subscriber, opens the locking circuit of relays 104 and 106 at armature 113. Relay 104, upon deenergizing, opens the circuit of relay 105 at armature 116, whereupon relay 105 deenergizes also. Relay 106, upon deenergizing, places ground on release conductor 127 at armature 122. When this occurs, sequence switch 200 of the incoming selector is driven out of position 17 and into position 18, whereupon the down-drive magnet operates as hereinbefore described, and the selector is restored to normal in the usual manner.

Regarding the freeing of the finder selector, such as the one shown in Fig. 9, when the incoming selector is driven to all trunks busy position as described above, it may be stated that the trunk finder and sender selector of the finder selector link are restored to normal in the hereinbefore described manner in response to the operation of sequence switch 600, which occurs when sequence switch 200 of the incoming selector advances beyond position 11 as described above.

Regarding the sender which is in use at the time that the incoming selector is driven to all trunks busy position, it may be said that the sender is freed in the usual manner in response to the removal of the ground potential from test brush 607 of the sender selector, Fig. 9, at cam 645 and its upper left-hand contact in response to sequence switch 600 moving beyond position 8 $\frac{1}{4}$.

In the sender, relay 712 now deenergizes owing to its being differentially wound, and closes a circuit for sequence switch 700 at armature 717 by way of the lower right-hand contact of cam 704 and said cam. Sequence switch 700 now advances from position 10 through its remaining positions and to position 1.

It will be noted that a ground potential 10 is kept on test conductor 752 of the sender through the lower winding of relay 712 until sequence switch 700 has advanced beyond position 18.

Referring now particularly to Fig. 9, the 15 operations of the sender selector element of the finder selector when all the senders are busy will be taken up. For this purpose, it will be assumed that the finder selector has operated in the usual manner until the 20 trunk finder element thereof has found the waiting trunk, and sequence switch 600 has been moved to position 3. It will be assumed further that the sender selector has not found an idle sender yet for the reason that 25 all the senders are busy. That being the case, the brushes 605-608, inclusive, of the sender selector are raised above the last set of terminals and relay 616 deenergizes in the usual manner, whereupon the circuit of updrive 30 magnet 601 is opened at armature 625, and sequence switch 600 is advanced from position 3 into position 4 upon the closure of a circuit which includes armature 625 and its resting contact and the upper left-hand contact of cam 647 and said cam.

With sequence switch 600 in position 4, ground is placed on the junction of relay 614 and resistance 630 by way of the following circuit: from ground by way of cam 640 and its upper right-hand contact, brush 610, and overflow commutator strip 613 (the elevator having been driven to overflow position). Relay 614 now deenergizes and closes at armature 629 a circuit for sequence switch 600 45 by way of the upper left-hand contact of cam 650 and said cam. Sequence switch 600 is driven from position 4 to position 12 in response to the closure of this circuit, and when position 12 is reached by sequence 50 switch 600, the trunk finder and sender selector are restored to normal in the hereinbefore described manner.

Obviously, conductor 866 is grounded at cam 640 in the usual manner when sequence switch 600 reaches position $6\frac{3}{4}$, whereupon sequence switch 850 of the finder selector allotter, Fig. 12, is advanced from position 1 in search of another idle finder selector, and when the second finder selector is reached, 60 it is driven from its waiting position 17 to position 1 in response to the closure of a circuit for its sequence switch at either cam 851 or 852 of sequence switch 850, depending upon which finder selector is found to be 65 idle. For example, when finder selector No.

1, Fig. 9, is standing in position 17, and is allotted by the finder selector allotter, sequence switch 600 is driven out of position 17 over the following circuit: from ground by way of cam 851 and its right-hand contact, conductor 864, lower right-hand contact of cam 647 and said cam, and the magnet of sequence switch 600 to battery. Sequence switch 600 in this case is advanced through position 18 and to position 1 by its local contact which does not open in position 18.

Under these conditions, when the next finder selector is allotted as above described, the common start conductor 246 is still grounded by the incoming selector, and the second finder selector is started to operating in the hereinbefore described manner to find the waiting trunk and to select an idle sender. In case an idle sender is found, the call goes through in the usual manner. If an idle sender is not found, however, the sender selector element of the finder selector is driven to overflow position with the results hereinbefore described, and the next finder selector is allotted and started into operation. This continues until one of the senders becomes idle and is selected.

It may be well to point out at this time why it is that the start wire is still grounded when the above mentioned overflow condition exists, at the time the next finder selector is allotted and is not grounded when the next finder selector is allotted under normal conditions. It will be remembered that ordinarily when the waiting trunk is found and after an idle sender has been selected, relay 614 remains energized, and when sequence switch 600 of the finder selector reaches position 5, a circuit is closed for the sequence switch of the incoming selector at cam 642 from the grounded conductor 865 and through the working contact of armature 619 of relay 614 and said armature. When the sequence switch of the incoming selector moves out of position 2 in response to the closure of this circuit, the ground is taken off the start wire and, consequently, the next finder selector is not started into operation when it is subsequently allotted. As pointed out above, however, relay 614 is deenergized when the sender selector is driven to overflow position and, consequently, no circuit is closed for the sequence switch of the incoming selector when sequence switch 600 of the finder selector reaches position 5, and the start wire remains grounded with the results hereinbefore described.

It will be understood that the drawings and the foregoing description merely set forth one desirable embodiment of the applicant's invention, and that the applicant does not desire to be limited to said embodiment, but to be limited only by the appended claims:

I claim:

1. In a multi-office telephone system, an automatic office comprising step-by-step switches for connecting subscribers' lines, a second automatic office comprising continuous motion power drive panel switches for connecting subscribers' lines, trunk lines for handling calls from the first office to the second office, register sets at the panel office for registering the digits of called numbers, other register sets, means for setting any one of said other register sets in accordance with the setting of any one of said first mentioned register sets, senders for operating the panel switches, and means for controlling the senders in accordance with the setting of said other register sets.
2. In an automatic telephone system, a plurality of senders for controlling the automatic switches, each sender comprising registering and sending apparatus, a plurality of registers for registering the digits in called telephone numbers, a common transfer circuit intervening between said registers and senders, means including a rotary step-by-step switch for connecting one end of said transfer circuit with busy registers one at a time, means effective each time for connecting the other end of said transfer circuit with an idle sender, and means for transferring numbers from the registers to the registering apparatus of the senders as fast as said connections are established.
3. In a telephone system, a register comprising two two-motion switches for registering four digits, a second register comprising four groups of relays, one group for each of four digits, means for associating said registers temporarily, and means for transferring a registered number from the first register to the second.
4. In a telephone system, a register set comprising two two-motion switches for registering four digits, a second register set also for registering four digits and comprising four individual registers, one per digit, means for temporarily associating said register sets, and means for transferring a registered number from the first register set to the second.
5. In a telephone system, a trunk line terminating in an automatic switch, registers, means for connecting an idle register to said trunk line, means for setting said register in accordance with impulses received over the trunk line, senders any one of which is adapted to control said switch, means for selecting an idle sender and for connecting the same to said trunk line, and means for placing the connected sender under the control of the connected register.
6. In a telephone system, a trunk line terminating in an automatic switch, a register, an automatic switch for connecting said trunk line with said register to enable the register to be set by impulses received over the trunk line, a sender for controlling said first switch, a third switch for connecting said sender with said trunk line, means for operating said third switch to connect said sender with said trunk line after said register has been set, and means for causing said register to control said sender.
7. In a telephone system, a trunk line terminating in an automatic switch, a register, a line switch individual to said trunk line for connecting the same to said register, a sender for operating said switch, means including a finder for hunting said trunk line and connecting the same to said sender, means controlled over the trunk line for setting said register, and means for causing the register to control said sender.
8. In a telephone system, a trunk line terminating in an automatic switch, a register, means for connecting said register with said trunk line at one point, means controlled over the two sides of said trunk line in series for setting said register, a sender, means for connecting said sender with said trunk line at another point, means for operating said switch, means controlled by said switch for operating said sender, means controlled by said sender for stopping the operation of said switch at a point determined by the setting of said register.
9. In a telephone system, a trunk line terminating in an automatic switch, a register for registering digits in a number, a sender for controlling said switch, means for causing the register to control the sender, and two independent and separately operable switching devices for connecting the register and sender, respectively, to said trunk line.
10. In a telephone system, a plurality of trunk lines, a plurality of register sets each common to all of said trunk lines, a plurality of register senders each common to all of said trunk lines, means responsive to a call on one of said trunk lines for rendering one of said register sets temporarily individual to such trunk line, means for thereafter setting the registers of the last named register set in accordance with a desired telephone number, means for rendering one of said register senders temporarily individual to the same trunk line, means for setting the last named register sender in accordance with the setting of the last named register set, and means for thereupon freeing said register set.
11. In a telephone system, a plurality of trunk lines, a plurality of register sets each common to all of said trunk lines, a plurality of register senders each common to all of said trunk lines, means responsive to a call on one of said trunk lines for rendering one of said register sets temporarily individual to such trunk line, means for thereafter setting the registers of the last named register set in accordance with a desired telephone number, means for rendering one of said register senders temporarily individual to the same trunk line, means for setting the last named register sender in accordance with the setting of the last named register set, and means for thereupon freeing said register set.

ting the registers of the last named register set over said trunk line and in accordance with a desired telephone number, means for rendering one of said register senders temporarily individual to the same trunk line, means for setting the last named register sender in accordance with the setting of the last named register set over a path independent of said trunk line, means for thereupon freeing said register set, and a train of automatic switches controlled by the set register sender to extend the trunk line to a called line.

12. In a telephone system, a trunk line, a plurality of registers, means for associating any register with said trunk line and for setting said register over said trunk line in accordance with a telephone number, a controlling device common to said registers, means for rendering said device temporarily individual to the operated register and for transferring the registration from the register to said device, and automatic switching mechanism operated by said device in accordance with said registration to extend a connection from said trunk line.

13. In a telephone system, a selective switch, means for extending a connection to said switch, a recording device responsive to impulses sent over said connection for storing designations, a plurality of equivalent switch controlling mechanisms, means independent of the extended connection for connecting any one of said mechanisms with the recording device, and means controlled by such mechanism for selectively operating the switch.

14. In a telephone system, a line, a selective switch, means for extending a connection from said line to said switch, a recording device controlled over said line for storing designations, a plurality of equivalent switch controlling mechanisms, means independent of the extended connection for connecting any one of said mechanisms with the recording device, means for connecting such mechanism with the switch, and means controlled by the connected mechanism for selectively operating the switch.

15. In a telephone system, a selective switch, means for extending a connection to said switch, a plurality of recording senders, means for sending impulses over the extended connection to set said senders, a plurality of equivalent switch controlling markers, means independent of the extended connection for connecting any one of said markers with any one of said senders, and means controlled by the connected marker for selectively operating said switch.

16. In a telephone system, a selective switch, automatic means for extending a connection to said switch, a plurality of senders for recording line designations, a plurality of equivalent switch controlling markers for

cooperating with said senders, a multi-contact relay device for connecting any sender to any one of said markers, and means controlled by the connected marker for selectively operating the switch to further extend the connection.

17. In a telephone system, a plurality of equivalent switches at a selective switching stage, means for extending a telephone connection to one of said switches, a plurality of recording senders each controlled over the extended connection for storing designations, a plurality of switch controlling markers, means independent of the extended connection for connecting any one of said markers to one of the senders, and means controlled by the marker for selectively operating the particular switch to which said connection has been extended.

18. In a telephone system, a plurality of succeeding switches for building up a connection, means for extending a connection to the first of said switches, a recording sender responsive to impulses sent over the extended connection for recording designations, a plurality of equivalent switch controlling markers, means independent of the extended connection for connecting any one of said markers to the recording sender, and means controlled by such marker for selectively operating each of said switches to further extend the connection.

19. In a telephone system, a selective switch, means for extending a connection to said switch, a recording device, a pair of equivalent markers arranged to be taken for use in alternation, means independent of the extended connection for connecting said recording device to one of said markers if idle and a succeeding marker if the first marker is busy, and means controlled by the connected marker for selectively operating said switch.

20. In a telephone system, a selective switching stage having a plurality of switches thereat, means for extending connections to said switches, a number of recording senders, a plurality of equivalent switch controlling markers, means for connecting any sender to any marker, means separate from the extended connection for connecting any marker to any one of said switches, and means controlled by the marker for selectively operating the switch to which it is connected.

21. In a telephone system, a plurality of selective switches, means for extending a connection to said switches, a plurality of recording senders, a plurality of equivalent switch controlling markers, means separate from the extended connection for connecting any one of said markers to any one of said senders, means separate from the extended connection for connecting any one of said senders to any one of said markers which is connected to a sender to any

- one of said switches, and means controlled by the connected marker for operating the switch.
22. In a telephone system, lines, a plurality of common senders for storing designations sent over said lines, progressively operable switches, a controlling mechanism common to said senders, means for connecting said mechanism with any one of the senders, and means under the direct control of said mechanism for directly operating said switches to extend said lines.
23. In a telephone system, telephone lines, a plurality of common senders for receiving and storing designations sent over said lines, progressively movable switches, a controlling mechanism common to said senders, means for connecting said mechanism with any sender, said sender arranged to transfer its designation to the controlling mechanism, and means controlled by said mechanism for directly moving said switches to extend said lines.
24. In a telephone system, lines a plurality of common senders for storing designations sent over said lines, progressively movable switches, a switch controlling mechanism common to said senders and also common to said switches, and means under the direct control of said mechanism for directly operating any one of said switches to extend said lines.
25. In a telephone system, lines, a plurality of common senders for receiving and storing designations sent over said lines, progressively operable switches, a controlling mechanism common to said senders and also common to said switches, means for connecting said mechanism with any sender, means for connecting said mechanism to one of said switches, and means controlled by said mechanism for directly advancing the switch.
26. In a telephone system, telephone lines, a plurality of common senders for storing designations sent over called lines, a plurality of progressively movable switches comprising a switching stage, a controlling marker common to said senders and common to said switches, means for connecting said marker with any of said senders, means for extending a calling line to one of said switches, means for connecting said marker to the particular switch to which said calling line is extended, and means under the control of said marker for operating said switch.
27. In a telephone system, lines, a plurality of common senders for receiving designations sent over said lines, a plurality of switches each arranged for a plurality of separate movements, a controlling mechanism common to said senders and common to said switches, means for connecting said mechanism with one of said senders, means for connecting said mechanism to one of said switches, and means for operating the switch to which such mechanism is connected in each of its movements.
28. In a telephone system, lines, a register sender for storing designations sent over said lines, progressively operable switches, a controlling mechanism normally disassociated from said sender, means for connecting said mechanism to said sender, means for connecting said mechanism to one of said switches, and means controlled by said mechanism for directly operating said switches to extend said lines.
29. In a telephone system, subscribers' lines, a register sender for receiving and storing designations transmitted over said lines, progressively operable switches, a switch controlling marker normally disassociated from said sender and from said switches, means for connecting said marker to said sender, means for connecting said marker to a desired one of said switches, and means under the direct control of said marker for selectively operating the particular switch to which said marker is connected for extending a subscriber's line.
30. In a telephone system, lines, a register sender for storing designations, progressively operable switches, a plurality of controlling mechanisms to which said sender is common, means for connecting said sender to any one of said mechanisms, and means under the control of the connected mechanism for directly operating one of said switches to extend a line.
31. In a telephone system, telephone lines, a plurality of common senders for receiving and storing designations, progressively movable switches, a plurality of controlling mechanisms common to said senders, means for connecting an idle mechanism to any one of said senders, means separate from the sender for connecting such mechanism to one of said switches, and means under the control of the connected mechanism for directly operating the switch to extend a telephone line.
32. In a telephone system, a telephone line, an automatic switch for extending said line, a selective switch having a plurality of separate directive movements, means controlled over said line for setting said selective switch in accordance with the numerical designation of the desired line, and means operated in accordance with the position taken by the selective switch for directly controlling the operation of said automatic switch.
33. In a telephone system, a telephone line, automatic switches for extending said line, selective switches each having a plurality of separate directive movements, means controlled over said line for setting said selective switches in accordance with the designation of the desired line, and means operated in accordance with the position taken by the selective switch for directly controlling the operation of said automatic switch.

lective switches for directively controlling the operation of said automatic switches.

34. In a telephone system, a telephone line, automatic switches for extending said line, a plurality of selective switches each having a plurality of separate directive movements, means controlled over said line for setting said selective switches in accordance with the numerical designation of the desired line, and means operated in accordance with the position taken by the selective switches for directively controlling the operation of said automatic switches.

35. In a telephone system, a calling line, a trunk circuit accessible to said line, register senders for controlling the operation of automatic switches to extend a connection, a switch associated with said trunk circuit adapted to select an idle one of said register senders, means for extending a connection from said line to said trunk circuit and for causing said switch to hunt for an idle one of said register senders, and means responsive to the calling party dialling during the hunting movement of said switch for stopping the hunting movement of said switch.

36. In a telephone system, a calling line, a trunk circuit accessible to said line, register senders for controlling the operation of automatic switches to extend a connection, a switch associated with said trunk circuit adapted to select an idle one of said register senders, means for extending a connection from said line to said trunk circuit and for causing said switch to hunt for an idle one of said register senders, a source of signalling current, and means responsive to the calling party dialling during the hunting movement of said switch for stopping the hunting movement of said switch and for connecting said source to said line.

In witness whereof, I hereunto subscribe my name this 30th day of October, A. D. 1922.

43

ARTHUR J. RAY.
